2,798,714

CONTINUOUS MINING APPARATUS OF THE PIVOTED BOOM TYPE

John D. Russell, Franklin, Pa., assignor to Joy Manufacturing Company, Pittsburgh, Pa., a corporation of Pennsylvania

Application July 5, 1949, Serial No. 102,995

17 Claims. (Cl. 262—29)

This invention relates to mining apparatus and more particularly to improved "continuous mining" apparatus for mining coal or other minerals from a solid seam or mine vein without the use of explosives, and for loading the material removed from the seam or vein as mining progresses.

From a broad aspect, the invention may comprise a mining and loading apparatus of a low height construction especially designed for use in underground mines having low head room and including vein-attacking and disintegrating mechanism for attacking segments of the coal or vein face in series to dislodge or tear the coal or other mineral in relatively large fragments from the coal seam or mine vein, and for receiving and collecting the dislodged material, and for conveying the material rearwardly from the face of the seam or vein to a suitable point where delivery to a conventional mine transportation system may be effected.

From a more specific aspect, the invention may comprise a mobile base such as a tractor base adapted to travel over the floor of a mine and carrying a swiveled frame mounted on the base to swing horizontally relative to the latter upon a vertical axis and on which horizontally swingable frame a sliding frame is supported and guided for rectilinear movement in a direction radial with respect to the vertical swivel axis, and on which sliding frame a swingable frame structure is pivotally mounted to swing in vertical planes with respect thereto about a horizontal axis at right angles to the direction of rectilinear movement. The swingable frame structure extends forwardly in advance of the base and carries vein-attacking and disintegrating mechanism. This swingable frame structure may be swung downwardly relative to the swivel frame and to the rectilinearly movable frame, to bring the outer portion of the vein-attacking and disintegrating mechanism near the mine floor, and the rectilinearly movable frame may then be moved by power devices radially outwardly to sum up the outer portion of the vein-attacking and disintegrating mechanism into the coal seam or mine vein. When the outer portion of the vein-attacking and disintegrating mechanism has been sumped into the coal seam or mine vein to the desired distance, the swingable frame structure may be swung upwardly by power devices about the horizontal transverse axis at a relatively rapid rate and with a powerful upward thrust, to effect dislodgment and disintegration of a vertical segment of the vein or seam between the top of the vein-attacking and disintegrating mechanism and the mine roof. The dislodged and disintegrated material will be moved rearwardly along the top of the vein-attacking and disintegrating mechanism to a material receiving means such as a conveyor having a forwardly and downwardly inclined portion extending to a point adjacent the rearward end of the vein-attacking and disintegrating mechanism and positioned to receive the disintegrated material discharged from the vein-attacking and disintegrating mechanism and to move the disintegrated material rearwardly and upwardly to a point from

2

which it is moved rearwardly of the apparatus preparatory to ultimate delivery to a mine transportation system. The rear end of the conveyor may discharge to another conveyor having a rearward material delivering end adjustable laterally of the apparatus. The forward end of the conveyor first mentioned may support a device for moving material relative to a mine floor as a preliminary to its clean-up, as, for example a pusher element or shovel which is arranged beneath the vein-attacking and disintegrating mechanism and which may move the loose material upon the mine floor, as the rectilinearly movable frame is advanced with the vein-attacking and disintegrating mechanism, in such a manner that it may be handled by the latter.

In various embodiments of my broad invention, the conveying means which has a portion extending forwardly and downwardly to a position to receive material from the vein-attacking and disintegrating mechanism may be a portion of a unitary conveyor of which the rear end is adapted to deliver to a delivery conveyor located at the rear of the apparatus, and the conveyor may be articulated to enable it to follow the vein-attacking and disintegrating mechanism as the latter is laterally repositioned, and may have a suitably controlled take-up means so that the forward portion may be fed and retracted while the point of discharge to the delivery conveyor remains unchanged; or, while an articulated forward conveyor may discharge to a delivery conveyor, it may have its rearward end advance—at least as far as the circulating conveyor and its rearward guide are concerned—and retract relative to an elongated receiving pan forming a part of the delivery conveyor; or the forwardly and downwardly extending conveyor portion may be a part of an unarticulated conveyor, swung as a whole about an upright axis and discharging in both its advanced and retracted positions to a hopper out of which an articulated conveyor takes material and delivers it to laterally different points.

When the vein-attacking and disintegrating mechanism reaches the end of its upward swinging movement the rectilinearly moving frame may be retracted by its power devices relative to the frame swiveled upon a vertical axis, to withdraw the outer portion of the vein-attacking and disintegrating mechanism from the face of the coal seam or mine vein.

The conveyor whose forward portion extends downwardly to a position at least adjacent the point of discharge of the vein-attacking and disintegrating mechanism, may be one with conveying means for transporting the disintegrated material along the upper portion of the apparatus, and the conveying means may have a swivel associated with it, whereby the forwardly and downwardly inclined portion may be brought by adjustment about the swivel to a plurality of differently angularly related positions across a face, and the forward portion of said conveying means, which may desirably be of the circulating chain and flight type, may be advanced and retracted with the vein-attacking and disintegrating devices.

The vein-attacking and disintegrating mechanism, when in lowered summing position near the mine floor, may be given a rectilinear summing movement so that the outer portion of the mechanism substantially extends the plane of the floor. The swinging movement of the vein-attacking and disintegrating mechanism is relatively rapid and powerful so that the coal or other mineral is rapidly dislodged from the coal seam or mine vein with a tearing action directed more or less towards the free face of the mine vein or coal seam.

Loose mineral or coal which falls to the mine floor from the vein-attacking and disintegrating mechanism needs to be gathered from the floor and delivered to the

conveying system. The sliding frame may carry, as above indicated, a pusher element or shovel in a position beneath the vein-attacking and disintegrating mechanism, and this, as the sliding frame is advanced with the vein-attacking and disintegrating mechanism, is adapted to move the material upon the mine floor into such relation to the vein-attacking and disintegrating mechanism that the latter may move the material forwardly and upwardly and then rearwardly and effect its discharge upon the front conveyor. The pusher element or shovel—the material moving device—may be pivotally supported on an axis parallel to the axis about which the vein-attacking and disintegrating mechanism is upwardly swingable, and power means may be provided for changing the level of the forward end of the pusher element or shovel with respect to the mine floor so as to position such end in a floor-clearing position, or well out of proximity to the floor for transport. The vein-attacking and disintegrating mechanism as it moves rectilinearly toward the working face in the different radial positions of adjustment thereof will move with it what might be termed the underlying portion of the conveyor, and the pusher element or shovel. The vein-attacking and disintegrating mechanism may comprise a series of parallel endless chains guided for circulation in upright orbital paths along parallel guideways on a vertically swingable frame structure, and the chains carry disintegrating elements so arranged that as the chains are rapidly circulated in their guideways, a series of fracturing or dislodging impacts are imparted to the coal or other mineral above the chains as the vein-attacking and disintegrating mechanism is swung upwardly, thereby to tear away or dislodge the coal or other mineral in relatively large fragments. The lower, forwardly moving runs of the chains are adapted, as the pusher element or shovel through its operation causes a mopping up of the material on the mine floor beneath the disintegrating mechanism, to trim the path and carry the material forwardly and around the front end of the disintegrating apparatus and over the top of the latter to the conveyor system. A dust-allaying liquid may be sprayed during vein disintegration for the purpose of minimizing the inconvenience and hazard of dust.

An object of the present invention is to provide an improved mining and loading apparatus especially designed for use in underground mines whereby the coal or other mineral to be attacked may be readily removed from a coal seam or mine vein and conveyed away from the face in a continuous operation and without the necessity for blasting. Another object is to provide an improved continuous mining apparatus which is extremely low in height and readily maneuverable. A further object is to provide an improved mining and loading apparatus having improved means associated with the vein-attacking and disintegrating mechanism for removing the coal or other mineral detached from the solid including improved means for receiving and collecting the disintegrated material irrespective of the position of adjustment in operation of the vein-attacking and disintegrating mechanism. A still further object is to provide an improved continuous mining apparatus in which a series of vertical segments of the coal seam or mineral vein are successively dislodged from the solid thereby completely removing the coal or other mineral across the working face, and wherein the dislodged coal or other mineral is rapidly moved as it is dislodged from the vicinity of the working face to a suitable point of delivery remote from the face. A still further object is to provide an improved self-contained mining and loading apparatus which comprises a mobile base having a swivel frame mounted thereon to swing horizontally with respect thereto and carrying a frame movable rectilinearly in a radial direction with respect to the swivel, on which rectilinearly movable frame is mounted a frame swingable in vertical planes and supporting a vein-attacking and disintegrating mechanism so that when the rectilinearly movable frame is moved out-

wardly with respect to the swingable frame, or is retracted, the vein-attacking and disintegrating mechanism is sumped into or withdrawn from the coal seam or mine vein, said apparatus having embodied therein means to effect swinging movement of the vein-attacking and disintegrating mechanism in vertical planes from its lowered sumped position to its raised position near the mine roof level and for retracting it after attainment to the desired upper position. Yet another object is to provide an improved mining apparatus having a novel, compact arrangement of parts resulting in extreme low height, while providing a powerful and rugged structure well adapted to meet the most severe demands of service. A further object is to provide, in an apparatus of the above character, an improved conveyor arrangement whereby at least a portion of the conveyor may be advanced and retracted with the rectilinearly movable frame, and this regardless of the different angular positions in horizontal planes of the vein-attacking and disintegrating mechanism, while yet the material may be delivered at a desired distance rearwardly of the vertical axis about which the vein-attacking and disintegrating mechanism is bodily horizontally adjusted. Yet another object is to provide improved fluid operated mechanism providing for advance and retraction of a material receiving conveyor portion with the material attacking and disintegrating mechanism, while yet providing for the delivery at the desired point, of the material received by said forward conveyor portion. A further object is to provide an improved driving means for a vein-attacking and disintegrating mechanism in which plural motors which are stationary as regards rectilinear movement relative to the base are connected through extensible driving connections to drive the opposite ends of a shaft which constitutes the driving element of the vein-attacking and disintegrating mechanism and which is moved bodily away from and towards said motors as summing and withdrawing take place. Still another object of the invention is to provide an improved arrangement for receiving material torn loose or dislodged by the disintegrating mechanism, including conveying means having a forward portion extending forwardly and downwardly beneath the rearward portion of the disintegrating mechanism and fed and retracted with the disintegrating mechanism as the latter is sumped and withdrawn. A still further object of the invention is to provide improved means for the cleaning up of material which may escape to the mine floor including pusher or shovel means advanced and retracted with the disintegrating mechanism as the latter is sumped and withdrawn, and so related to the disintegrating apparatus that the latter may handle the material moved by said pusher or shovel means. Another object is to provide in a mining and loading apparatus of the character above referred to, an improved mechanism for cleaning up the mine floor in advance of the base of the apparatus, with such mechanism mounted to move horizontally into different angular positions with the vein-attacking and disintegrating mechanism and to move rectilinearly back and forth with the vein-attacking and disintegrating mechanism. A still further object is to provide receiving means for the disintegrated mineral mounted on the base of the apparatus and arranged and constructed so that it receives disintegrated mineral discharged from the vein-attacking and disintegrating mechanism irrespective of the position of angular and rectilinear adjustment of said mechanism. Yet another object is to provide an improved material moving means on the base for moving the disintegrated mineral from said receiving means to a point remote from the face of the mineral vein. These and other objects and advantages of the invention will, however, hereinafter more fully appear.

In the accompanying drawings there are shown for purposes of illustration three embodiments which the invention may assume in practice.

In these drawings:

Fig. 63 is a diagrammatic view illustrating the hydraulic fluid system and associated control means.

Figs. 64 and 65 are respectively diagrammatic plan and side views, showing operations in a mine.

In Figs. 1 to 23 of the drawings, I have illustrated one embodiment of my invention, and in Figs. 24 to 28 I have illustrated another embodiment; and in Figs. 29 to 65 I have illustrated still a further embodiment of my invention in its broader aspects, this time incorporated in an apparatus which in many of its features is the

invention of one John R. Sibley and which is disclosed, and claimed as to the features thereof which are his invention, by the said Sibley in application Serial No. 102,996, filed of even date herewith.

Describing first the illustrative embodiment of Figs. 1 to 23, it will be noted that the mining and loading apparatus generally comprises a mobile base 1, herein preferably a tractor or crawler base, having a frame 2 which has swiveled thereon at 3, to swing about an upright axis in horizontal planes with respect thereto, a horizontally extending supporting frame 4. The swiveled supporting frame 4 has a horizontal portion 5 extending forwardly, and guided on this horizontal frame portion for movement rectilinearly relative thereto in a radial direction relative to the swivel axis is a sliding frame or support 6 on which a swingable frame or bar structure 7 is pivotally mounted on a horizontal transverse axis 7' to swing in vertical planes with respect thereto and to swing horizontally with the swiveled supporting frame 4 relative to the base 1. The vertically swingable frame or bar structure 7 extends forwardly in advance of the swiveled frame with its pivotal axis located, even when the sliding frame or support 6 is retracted, a substantial distance in advance of the base. The swingable frame structure 7 carries a mine vein-attacking and disintegrating mechanism or so-called disintegrating head generally designated 8 for attacking and disintegrating the coal or other material in vertical segments from a solid coal seam or mine vein. The vein-attacking and disintegrating mechanism 8 when disposed in a horizontal position as shown in Fig. 1 has its upper limits disposed below the upper limits of the apparatus, thereby providing a construction which is extremely vertically compact.

Conveying means generally designated 9 is provided for receiving disintegrated material as it is brought back by the vein-attacking and disintegrating mechanism, and for moving it rearwardly away from the face of the mine vein. This conveying means includes a forward material-receiving portion 10, extending forwardly and downwardly beneath the rearward portion of the disintegrating mechanism for receiving disintegrated mineral discharged from the latter, and has associated with such forward portion 10 a pusher element or shovel 11 extending forwardly and downwardly beneath said disintegrating mechanism for moving disintegrated mineral which may fall to the mine floor from the vein-attacking and disintegrating mechanism into such relation to the latter that it may be picked up thereby and deposited in the conveyor system. The conveying means 9 also includes, in this embodiment of the invention, a rearward material delivering portion 12. The conveying means includes—or is provided with—arrangements for permitting the forward portion to be advanced and retracted, and to assume different angular relations, relative to the rearward portion, so that it may be moved forward as the disintegrating mechanism is sumped and moved rearward as the disintegrating mechanism is retracted, without interrupting the flow of material, and may be capable of underlying and receiving material from the disintegrating apparatus, in the different lateral positions of the latter, during sumping and withdrawing at different points across the mine face.

Turning now for a time from the conveying means and shovel or pusher element, it may be noted that a pair of motors 13, 13 are carried by the swiveled supporting frame 4, and these motors serve to drive the vein-attacking and disintegrating mechanism 8. A pair of reversible motors 14, 14 individually drive endless crawler treads 15, 15 of the tractor base, and a single motor 16 drives the conveying means 9. A motor 17 drives a pumping means 18 for delivering liquid under pressure to various hydraulically operated devices of the apparatus. All of

the motors are preferably, but not necessarily, electric motors.

The crawler treads 15 of the tractor base serve to support and to propel the apparatus and to effect steering thereof.

By swinging the vein-attacking and disintegrating mechanism 8 about the swivel axis 3 of the supporting frame 4, it may be brought into different radial positions relative to the base 1, to attack and disintegrate 10 the coal seam or mine vein in a series of vertical segments of the working face, so that the entire width of the working face may be dislodged and disintegrated in successive steps.

The conveying means 9 is adapted to discharge into a 15 widened hopperlike portion 19 of a laterally adjustable tail or rear discharge or delivery conveyor 20, which is driven by a motor 21, likewise preferably an electric motor, and which is laterally adjustable at its rear end to permit delivery of material which it receives in its laterally widened portion 19, at any desired point within its reach.

The frame 2 of the tractor or crawler base 1 is a built-up structure and comprises an arcuate portion 22 arranged in a low position forwardly of the tractor treads and having an inverted L-shaped flange 23, which supports and guides a shoe portion 24 which is fixed to and herein shown as integral with a portion of the swiveled frame 4. Transversely extending, upstanding walls 26, 27 cooperate with various horizontal transverse plates 29, 30, 31 and 32 30 and upright longitudinally extending plate portions 33 (shown in Fig. 18) to support fixed tubular bearing support elements 36 and 37. These are surrounded by bearing sleeves 38, and the latter in turn lie within ear-like elements 39 and 40, which are suitably fixed with respect 35 to the rearward portion of the horizontally swingable frame structure 4, each being secured as shown to a transverse plate element (41 and 42) secured as by welding to and forming a part of the frame 4. The frame 4 has horizontally swingable with it about the axis 3, a horizontal plate portion 44 which provides a support for the lower run of a flight conveyor chain 45, and the upper run of this chain is supported by a plate 46 shaped similarly to the plate 44 and carried above the bearing member 37 and swingable with the frame 4. Plates 44 40 and 46 are of maximum width at a point adjacent the axis 3 and they are curved at their rearward ends on arcs struck from said vertical axis, and they cooperate with correspondingly concaved plate portions 49 and 50 which respectively form parts of rearward guide plates for the 45 flight conveyor chain 45. The frame 4 is swingable about the axis 3 by hydraulic cylinder and piston mechanisms 60, 61 pivotally connected at 62, 62 to ears 63, 63 secured in fixed relation to the frame 4, and at their rear ends the cylinder and piston mechanisms are secured by 50 pivots 64, 64 to a suitably reinforced rear end member 65 of the frame 2. It will be evident that when fluid is supplied to one end of one of the cylinder and piston mechanisms 60, 61, and simultaneously supplied to the other end of the other, there will be a lateral swinging 55 in one direction or the other of the frame 4 about the vertical axis 3. The cylinder and piston mechanisms 60, 61 are double acting, and a suitable fluid supply and venting system for them is illustrated in the diagrammatic view of Fig. 23. It may be noted at this point that the 60 member 65 provides a support for the tail or delivery conveyor 20, heretofore mentioned. The matter of this support will be later more fully described.

The horizontal forward portion 5 of the swiveled supporting frame 4 has laterally spaced parallel side portions 71, 71 having curved upright surfaces 72, 72 at their adjacent sides; and the motors 13, 13 are secured to the outer sides of these side frame portions as shown in Figs. 6, 7 and 18. The side frame portions 71 have vertical outside walls 74 to which the motors 13 are secured, to 75 provide rigid supports for the latter. Extending longi-

tudinally along the inner sides of the side frame portions 71 are horizontal guideways 75 which receive laterally spaced, rearwardly extending guides 76 fixed relative to the sliding frame or support 6. The sliding frame or support 6 also has guide portions 77 secured to the side portions 78 of the sliding frame and which slide on guide members 79 formed on the forwardly extending portion 5 of the swivel frame 4. Suitable hydraulic means is provided for reciprocating the sliding frame or support 6, and for this purpose I employ double acting hydraulic feed cylinders 80, 80 arranged longitudinally along the inner sides of the parallel side frame portions 71 of the swiveled supporting frame 4, these being connected at their rear ends as at 81 within and to the frame portions 71, and at their forward ends pivotally connected as at 82 to lugs 83 secured to the side portions 78 of the sliding frame 6. When liquid under pressure is supplied to one end or the other of the cylinders 80, their pistons may be moved to feed the sliding frame 6 rectilinearly back and forth along the guideways 75 and 79. By trapping liquid in the feed cylinders, the pistons may be locked in position to hold the sliding frame against sliding movement. The means for supplying liquid under pressure to the cylinders 80 will later be described. It will be noted that the shoe portion 24, previously mentioned, is arranged between the rearward ends of the forwardly extending guides 79, 79.

The means for swinging the frame structure 7 which carries the vein-attacking and disintegrating mechanism 8 comprises a pair of single acting hydraulic cylinders 85 containing pistons 86 having piston rods 87 which are pivotally connected at 88 to depending brackets 89 secured rigidly to the lower rearward portions of the frame structure 7. These cylinders are arranged parallel to each other at the outer sides of the gathering head or shovel 11, and are suitably pivotally connected at 90 to and supported by the spaced front side portions 78 of the sliding frame 6. When liquid under pressure is supplied to the rear ends of the cylinders 85, the pistons 86 are moved forwardly to swing the frame structure 7, together with the vein-attacking and disintegrating mechanism 8 carried thereby, upwardly about the pivot 7'. By trapping liquid in the cylinders 85, the frame structure may be locked in adjusted position, and by appropriately venting liquid from the cylinders, the frame structure may be allowed to swing downwardly about its pivot at a controlled rate. The means for supplying liquid under pressure to and for venting liquid from the cylinders 85 will later be described.

The vein-attacking and disintegrating mechanism 8 comprises a series of endless disintegrating chains 91 guided in parallel guideways 92 for circulation in vertical orbital paths. Each chain comprises a series of chain blocks 93 pivotally connected by intermediate strap links 94 which are pivotally connected to the blocks 93 by hinge pins 95. The blocks have the usual gibs at their bases received in the guideways, and projecting laterally from the blocks are lugs 97 which have sockets for receiving disintegrating elements, herein in the form of conventional cutter bits 98 held in position on the lugs by conventional set screws 99. The disintegrating bits on the chain may be arranged in various manners, as for example in accordance with the showing in the application of Harold F. Silver, Ser. No. 11,688, filed Feb. 27, 1948, according to which the bits are set in slightly oblique transverse rows. I have, however, illustrated what seems to me a somewhat preferable arrangement, which is more fully shown in Figs. 29, 30, 33, 51 and 52 and herein-after described in connection with those figures.

Now referring to the improved driving connections between the motors 13 and the disintegrating chains 91, it will be noted that arranged with its axis in the same line with the pivot 7' there is a transverse drive shaft 104 suitably journaled in bearings 105 supported in brackets 106 secured to the front side portions 78 of the sliding

frame 6. Keyed to this shaft 104 is a series of chain sprockets 107 which engage and drive the endless disintegrating chains. Also keyed to the shaft 104 between the chain sprockets are impeller elements 108 for ejecting the disintegrated material from between the chains as the latter travel around the chain sprockets. Each motor 13 has a horizontal tubular motor shaft 111 (see Fig. 6) journaled in bearings 112 supported within the motor heads. The rear end of this shaft is connected through a preloaded slip friction clutch (not shown) housed in a casing 116 carried by the rear end of said tubular shaft 111, to a drive shaft 119 which extends forwardly within the tubular motor shaft, as shown in Fig. 6. The shaft 119 has a splined connection at 120 with a tubular shaft 121, also arranged within the motor shaft and keyed at its forward end to an inner element 122 of a universal coupling 123. Secured to the outer element 124 of this coupling is a shaft 125 suitably journaled in bearings 126 supported within a gear housing 127 attached to the outer side portions of the sliding frame 6. Keyed to each shaft 125 is a spur gear 128 meshing with a large spur gear 129 which is keyed to a longitudinal shaft 130, likewise suitably journaled within bearings supported within the gear housing. Fixed to or integral with each of the shafts 130 is a worm 131 meshing with and driving a worm wheel 132 having its hub 133 suitably journaled on bearings 134 supported by a transverse shaft 135, the latter in turn being supported within the gear housing. Integral with each of the gear hubs 133 is a spur gear 136 meshing with a large spur gear 137 which is keyed to the adjacent end of the transverse shaft 104. Thus, the shaft 104 is driven at both ends, and as the sliding frame 6 is moved along its guideways, the drives between the motors 13 and the opposite ends of the shaft 104 are maintained through the self-adjusting telescopic shaft connections. By arranging the motors 13 at opposite sides of the frame 4, a low, compact, symmetrical and well balanced design is attained.

The conveying means 9 will now be further described. As previously noted, it includes a forwardly and downwardly extending portion 10 which is advanced and retracted with the sliding frame 6 and which is guided in guideways provided by a trough-like frame 140 on the sliding frame 6. The conveyor is of the single chain, flight type and includes the central chain 45, previously mentioned, having extending transversely thereof, at suitable intervals, flight bars 141, secured thereto, for moving the disintegrated material along top plates provided by a plurality of elements shortly to be described. The conveyor chain 45 at the front receiving end of the conveyor passes around a front idler roller 142 (see Figs. 3, 6 and 12) secured to a transverse sleeve 143 supported by stub shafts 144 journaled in bearings 145 supported by brackets 146 secured to side frames 147 secured to the side portions 78 of the sliding frame 6. The conveyor chain 45, at the rear, discharge end of the conveying means, passes around a drive sprocket 148 secured to a tubular shaft 149. This shaft 149 is suitably supported by bearings carried by side plates 150 carried by the base 2. The chain also extends forwardly, beneath its upper run, to an idler sprocket 151 supported by a shaft 152 suitably rotatably supported by the side plates 150, and after passing around this relatively fixed idler sprocket the chain again passes rearwardly and about a movably supported sheave or idler sprocket 154, and then forwardly through openings within the frame structure and finally downwardly to the idler roller 142. The idler sprocket 154 is mounted on a transverse shaft 155 supported as shown by a shaft 156 mounted on blocks 157 slidably guided in horizontal slots 158 in the side plates 150. The blocks are adapted to be moved forwardly in the slots, to supply the necessary slack for the sumping-movement-attending, forward travel of the idler roller 142. To effect the opposite movements of the blocks 157 there are connected to the latter piston rods 160 which are at their other ends

connected to pistons 161 received in double acting "slave" cylinders 162. The cylinders 162 are carried by the opposite ends of a transverse plate 163 having limited sliding movement longitudinally of the apparatus in slots 164 formed in the side plates 150 in parallelism with the guide slots 158, and are adapted to provide for these pistons strokes equal in length to the sumping and withdrawing strokes of the disintegrating mechanism as the latter is sumped and withdrawn by the cylinder and piston mechanisms 80. The position of the transverse plate 163 is shiftable, as will shortly be described, by a cam mechanism which is provided to compensate for changes in chain tension as the disintegrating apparatus and the forward end of the conveyor are shifted laterally to enable disintegrating operation on laterally differently spaced segments of the face.

The pusher element or shovel 11 has parallel rearward frame portions 170 (Fig. 12) arranged inwardly of the side frames 147 which guide the forward portion 10 of the conveying means 9. These shovel side portions engage bearings 171 supported by the bearing brackets 146. Thus the pusher element or shovel may swing in vertical planes about an axis coincident with the axis of the front idler shaft 143 of the front conveyor portion. The shovel 11 has a widened mouth, as shown in Fig. 12, provided with a front edge 172 which is adapted to engage the mine floor. Pivotedly mounted at 173 between depending lugs 174 integral with the forward portion of the sliding frame 6 is a boss 175 carried at the rear end of a cylinder 176. The cylinder 176 contains a reciprocable piston 177 having a piston rod 178 extending downwardly through the lower or forward head 179 of the cylinder 176. The piston rod is pivotally connected at 180 with ears 181 secured to a portion 182 of the shovel which lies to the rear of the idler shaft 143. Thus, when pressure is supplied to the rearward end of the cylinder 176, the edge 172 of the shovel or pusher element will be raised above the mine floor, and when pressure is vented from said end of the cylinder 176, the forward end of the shovel will be permitted to swing downwardly into adjacency to or into actual contact with the mine floor. The means for supplying pressure fluid to the cylinder 176 will be later described, but it may be noted that the cylinder and piston mechanism 176, 177 is a hydraulically operated device in the illustrative construction shown.

It may be noted now that the forward portion 10 of the conveying means 9 is supported in the upper run thereof by a forwardly and downwardly inclined plate portion 183 at the rearward or upper end of which there is a horizontal plate portion 184 is reciprocable with and forms a part of the reciprocable frame 6 and which extends, in its rearmost position, just to the rear of the vertical axis 3. The lower run of the conveyor is supported at opposite sides of the junction of inclined (185) and horizontal (186) support portions by such portions, which are fixed with respect to and form a part of the reciprocating frame 6. Rearward of the support portion 186 there is the laterally pivotable plate 44, heretofore described, and at the rear of the plate 44, the plate 49 slopes downwardly and rearwardly, and from the lower edge of plate 49, a relatively long horizontal plate element 188, extending between the side plates 150 runs all the way back to a point 189, underlying the shaft 155, which supports the adjustable take-up sheave or sprocket 154. Underlying the rearwardly extending chain run which extends between the sheave or sprocket 151 and the sprocket 154 is a transverse plate 190 extending between the side plates 150; and another support plate 191 extends rearwardly from the sprocket 151 to a position slightly short of the sprocket 148, and this support plate 191 has a downwardly turned rear end 192 to guide the forwardly moving conveyor elements onto its upper surface. The rearward portion of the upper run of the conveyor is guided by a plate 193 whose forward end extends to and includes the plate portion 50 previously described.

The plate 190 is reciprocable with the sprocket 154, longitudinally of the apparatus. The plate 193 flares at its forward end to provide additional width of surface to underlie the flight conveyor as the latter at its forward end is swung to one side or the other as the parts are positioned for attacks on a mineral vein at opposite sides of the center thereof.

For the purpose of guiding the upper run of the flight conveyor as the swiveled frame 5 is moved to differently laterally adjusted positions and as the sliding frame 6 is moved forward and retracted, I have provided flexible side boards 200, these being made of suitable steel plate, suitably alloyed and treated for resilience and wear resistance. The forward ends of these upright side boards are fixed in any suitable manner to walls 201 formed at the rearward end of side wall portions 202 on the reciprocable frame 6. At their rearward ends these side boards, which, it will be evident, reciprocate relative to the relatively stationary frames 1 and 4, extend, in the retracted position of the sliding frame 6, to a point relatively near the rear end of the frame 2 and to the sprocket 148. They lie at their bottom edges in spaces between the ends of the flights and the upright side plates 150, and are slidably guided at their inner sides at their upper edges by inverted U-shaped clips 205 secured to the side plates by screws or the like 206. The clips are relatively near the rear of the fan shaped plate 46, so that there is available a substantial length of the side boards for sliding movement as their forward end portions advance and are retracted on the order of 18 inches or thereabouts. It will be apparent that as the swiveled frame 5 is swung laterally upon the upright axis 3, the flexible side board members will be swung laterally to provide arcuate or curved guide surfaces for the ends of the flights of the conveyor chain and will prevent escape of disintegrated material as the same is moved along by the flights. Also as the sliding frame 6 is fed forward and retracted, there will be, regardless of the angle of the frame 4 to the base 1, a forward and rearward sliding of the side boards which will provide lateral guide surfaces at the edges of the path of the flight conveyor. The curved upright surfaces 72, 72 guide the side boards 200 in such a manner as to confine them to material-escape-preventing positions.

As the swiveled frame 5 is swung in one direction or the other out of the position in which it is aligned with the frame 1, the center line of the chain 45 of the conveyor will move to one side or the other of the vertical axis 3, and the farther away from this vertical axis the path of the chain lies, the more slack there will tend to be introduced into the chain. I say tend to be, because I have provided means for preventing the occurrence of any undesirable slack, and this means includes a cam 210 secured as by screws 210' to a portion of the member 40 to the rear of the axis 3. This cam is not struck on an arc having its center in the axis 3, but instead has a much flatter curvature, so that radial distances to points in the cam surface measured from the axis 3 increase toward the ends of the cam and are at a minimum at the center of the cam. The cam 210 is adapted to engage a roller 211 on a strut member 212 of box-like construction, which is guided by rollers 213 engaging its opposite edges, these rollers being supported on stationary pivots 214 and arranged at the rear of the plate 32 and supported by plates 215, as shown in Fig. 19. The rear end of the strut member 212 is bolted as at 216 to the cross plate 163, which is bolted as at 218 to the cylinders 162 which, with their pistons 161, determine the position of the take-up sprocket 154. The cylinders' engagement with the side plates and the engagement of the rollers 213 with the strut member 212 cause the strut member and the cross plate 163 to move rectilinearly with respect to the center line of the apparatus. When lateral swinging of the frame 4 will tend to introduce slack in the conveyor chain, coaction of the cam 210 with the roller 211 will force the take-up

sprocket rearwardly and thus prevent the occurrence of slack in the conveyor chain.

If it be understood that the cylinders 162 are filled with hydraulic fluid at opposite sides of the pistons 161 therein at all times, it will be apparent that the cam mechanism described will effect a shifting of the idler sprocket 154 in precise harmony with the movement of the cam roller 211 and of the strut member 212. When there is lateral swinging of the frame 4, this will not, in view of the provision of the foregoing mechanism, cause an undesirable change in the tension of the conveyor chain.

Summing movement of the disintegrating apparatus 8 can take place only if the take-up sprocket is moved forwardly an amount equal to the movement of the roller 142, and to cause this desired movement to take place, I have provided another hydraulic cylinder 220—more than one may be employed—and in this case have arranged it as shown in Fig. 3, where it will be noted that the cylinder 220 is carried by the laterally swingable frame 4 and is secured at its rear end, as at 221, to the cross plate element 42. The cylinder 220 is a "master" cylinder and contains a piston 222 (see Fig. 22) provided with a piston rod 223 connected to a member 224 which reciprocates with the sliding frame 6, herein secured to the plate 183 being illustrated. Now this "master" cylinder 220 is arranged midway between the sides of the laterally swingable frame 4, and accordingly, irrespective of the angle occupied by the frame 4 to the main frame 2, the same length of summing movement will cause the same amount of piston movement, and a given length of withdrawal movement will cause a given length of piston movement. This "master" cylinder 220 is filled at both sides of the piston with a hydraulic fluid, and there is a connection between the head end of this cylinder and the head ends of the slave cylinders 162; and also between the forward end of this cylinder and the rearward ends of the slave cylinders. The displacement of the piston 222 upon its movement relative to the cylinder 220 will be made such with reference to the displacement of the pistons 161 in the slave cylinders 162 that for a unit length of movement of the piston 222 there will be the same unit length of movement of each of the pistons 161 in like direction, and accordingly the idler sprocket 154 will be caused to move forward and rearward in precisely the amounts that the idler roller 142 is moved forward and rearward during summing and withdrawal movements of the disintegrating apparatus 9, which movements are attended by equal movements in the same directions of the idler roller 142. It will be of course understood that, instead of a single master cylinder 220, there may be two master cylinders, one associated with each of the slave cylinders and each having one-half the fluid displacement of the master cylinder 220, and accordingly the same displacements essentially as the slave cylinders with which they are individually associated. Each of the two master cylinders would then have its forward end connected to the rear end of its associated slave cylinder and its rear end connected to the forward end of its associated slave cylinder.

It will now be clear that if there is no lateral swinging of the frame 5, the cam mechanism above described will not effect any shifting of the idler roller, and that feeding and retracting movements of the disintegrating mechanism will be attended by equal forward and rearward movements of the take-up sprocket 154, and the chain tension will be maintained the same. If the frame 4 is moved laterally, the cam 210 will maintain the chain tension substantially uniform, and if the disintegrating mechanism is summed and withdrawn in one of the laterally adjusted positions thereof, the tension of the conveyor chain will none the less be maintained substantially uniform, because the master—slave cylinder arrangement will cause this result automatically to take place. The mounting of the slave cylinders 162 for control of their position by the cam-strut mechanism provides for either or both controls of the position of the take-up sprocket to operate

effectively. As shown in Fig. 22, it will be apparent that two conduits 225 leading from the forward end of the master cylinder 220 are connected to the rear ends of the slave cylinders 162, while two conduits 226 lead from the rear end of the master cylinder 220 and are connected to the forward ends of the slave cylinders 162.

It will be observed that the point of delivery of the flight conveyor is constant, with respect to the base 1, with the construction shown, and also that the flight conveyor delivers material only at the center line of the apparatus. In order to permit delivery of material other than directly behind and in line with the apparatus, I have provided, as above stated, a tail or delivery conveyor 20 consisting of a trough 230 having an enlarged material receiving portion 19, and the enlarged material receiving portion is supported, by horizontal transversely extending pivots 231, on ears 232 which are arranged at the opposite ends of a member 233 pivoted to swing on a vertical axis 234 between cars 235 carried by the base frame 2. A suitable conveyor 236, herein shown as a chain and flight conveyor, extends from the enlarged portion 19 of the trough 230, where it passes around sprockets 237 carried by a shaft 238, to a rear sprocket carrying shaft 240 which is driven by a chain and sprocket drive 241 from the motor 21 through a reduction gearing (not shown) housed in a housing 242. The angular position in elevation of the tail conveyor may be controlled by a hydraulic cylinder and piston mechanism 244, 245, of which the elements are connected by links 246 and 247 respectively to a pivotally supported member 248 turnable about a stub shaft 249 in line with the pivot axis 234, and to a yoke 250 pivotally connected to the sides of the trough 230 as at 251. Upon admission of fluid at the rearward end of cylinder 244, the delivery end of the delivery conveyor may be raised. On bleeding of fluid from the cylinder 244, the delivery end can be lowered. The position of discharge of the delivery conveyor can be varied by moving its rearward end laterally about the aligned axes of the pivots 234 and 249.

The hydraulic fluid system and associated control means, as shown diagrammatically in Fig. 23, includes the pumping means 18 driven by the motor 17, and the pumping means has its suction side connected through a conduit 254 to a liquid reservoir or tank 255. The discharge side of the pumping means is connected through a conduit 256 to the supply passage of the valve box of a conventional valve mechanism 257. The discharge passage of the valve box is connected through a return conduit 258 back to the tank. The valve box may assume various forms but is herein made up of a series of valve block sections 259 and end sections 260 and 261, and these sections are suitably secured in assembled relation. The end section 260 has an inlet chamber formed therein to which the supply conduit 256 is connected and the end section 261 provides the discharge chamber to which the discharge conduit 258 is connected. Associated with the inlet section 259 is a conventional safety valve 262 for connecting the inlet chamber to the discharge passage in the event of overload in the system. The valve block sections 259 have horizontal bores containing conventional slide valves of the balanced spool type, respectively designated 263, 264, 265, 266 and 267. The bore containing slide valve 263 is connected by a conduit 270 to the tilt cylinder 244 of the hydraulic cylinder and piston mechanism of the tail conveyor 20. The bore containing the slide valve 264 is connected by a conduit 273 to the tilt cylinder 175 for the shovel or pusher element 11. The bore containing the slide valve 265 is connected through conduits 274 and 275 respectively having branches which lead to the opposite ends of the cylinders of the cylinder and piston mechanisms 60 and 61 for swinging the swiveled frame or turntable 4 about its swivel axis. The bore containing the slide valve 266 is connected through a conduit 276 to the rearward ends of the swinging cylinder

ders 85 for the vein-attacking and disintegrating mechanism 8. A conventional relief valve 277, set to open at a predetermined pressure in the elevating cylinders, is connected by a conduit 278 to the return conduit 258 so that the swinging cylinders may be connected to exhaust in the event of excessive pressures therein. The bore containing the slide valve 267 is connected through conduits 279 and 280 to the opposite ends of the feed cylinders 80 for feeding the vein-attacking and disintegrating mechanism and the pusher or shovel back and forth along the guideways on the swiveled supporting frame or turntable. The master cylinder 220 is connected at its opposite ends through conduits 225, 225 and 226, 226 to the opposite ends of slave cylinders 162, as above described, thereby to provide a closed fluid system. Any suitable filling means for this closed fluid system may be provided. As is conventional in a valve mechanism of the type disclosed, bypass means is provided for permitting free flow of fluid between the inlet chamber and the discharge chamber past the valves when the latter are positioned midway in their respective bores in the valve box and flow to the various cylinders is cut off.

The general mode of operation of the mining and loading apparatus above described is as follows: The apparatus may be propelled about the mine and steered by the motors 14 which drive the crawler treads 15. When the apparatus assumes its operating position at the working face of a coal seam or mine vein, the motor 17 which drives the pumping means 18 may be operated to effect building up of a pressure in the hydraulic system, and liquid under pressure may be supplied to the cylinder and piston mechanisms 60 and 61 under the control of the slide valve 265, to effect the swinging of the vein-attacking and disintegrating mechanism 8 laterally to the right until its outer end portion assumes a position near the right hand rib. When the vein-attacking and disintegrating mechanism is properly positioned at the right hand rib the valve 265 is positioned to trap the liquid in the swinging cylinders to lock the swivel frame 4 in position, and the slide valve 266 which controls liquid flow with respect to the swinging cylinders 85 may then be positioned to cause the vein-attacking and disintegrating mechanism to swing downwardly until its outer end portion assumes a position near the level of the mine floor. The slide valve 264 may then be positioned to effect downward swinging of the pusher or shovel 11 to bring its front edge close to or in contact with the mine floor. The motors 13 and 16 may then be operated to effect circulation of the endless disintegrating chains and the conveyor chains within their guideways. The slide valve 267 which controls liquid flow with respect to the feed cylinders 80 may then be positioned to supply liquid under pressure to the rear ends of the cylinders to effect forward feeding movement of the vein-attacking and disintegrating mechanism to sump the outer end portion thereof into the coal seam or mineral vein. When the outer end portion of the vein-attacking and disintegrating mechanism has been sumped into the coal or mineral, liquid may be trapped in the feed cylinders 80 to lock the sliding frame 6 in its advanced position, and the slide valve 266 may thereafter be positioned to supply liquid under pressure to the rear ends of the swinging cylinders 85 to effect upward swinging of the vein-attacking and disintegrating mechanism, to tear out and disintegrate the coal or mineral between the top of the vein-attacking and disintegrating mechanism and the mine roof. During upward swinging movement of the vein-attacking and disintegrating mechanism the swinging cylinders and pistons impart a rapid and powerful upward thrust to the orbitally moving disintegrating chains so that the coal or mineral is broken or torn loose in relatively large fragments from the face. Upon completion of the upward swinging operation and when the outer end portion of the vein-attacking and disintegrating mechanism has assumed its raised position near the roof, liquid may be trapped in the swinging cylinders 85

and the slide valve 267 may then be positioned to supply liquid under pressure to the front ends of the feed cylinders 80 to effect withdrawing movement of the vein-attacking and disintegrating mechanism to remove its outer portion from the face. As the vein-attacking and disintegrating mechanism is fed forward by the feed cylinders 80 the piston 222 in the master cylinder 220 is moved forwardly with the sliding frame, forcing liquid from the front end of the cylinder through conduits 225 to the rear ends of the slave cylinders 162, causing the pistons 161 therein to move forwardly, thereby to move the idler sprocket 154 forwardly a corresponding distance, so that the front idler 142 may make its forward movement. Conversely, when the vein-attacking and disintegrating mechanism is fed rearwardly by the feed cylinders 80 the piston 222 in the master cylinder 220 forces liquid from the rear end of the cylinder through conduits 226 to the front ends of the slave cylinders 162 forcing the pistons 161 rearwardly thereby to move the idler sprocket 154 rearwardly to take up the conveyor-chain slack which would otherwise be produced by the rearward movement of the idler 142. As the vein-attacking and disintegrating mechanism was swung horizontally about the swivel axis 3, the cam 210 which swings horizontally with the swiveled frame 4 effected, through the slideable strut member 212, longitudinal movement of the slave cylinders 162 and the idler sprocket 154, and took up the slack which would otherwise have been introduced in the conveyor chain as a result of such lateral swinging of the forward portion of the conveying means 9 with the vein-attacking and disintegrating mechanism. During the sumping, swinging and withdrawing operations of the vein-attacking and disintegrating mechanism, the coal or mineral torn loose and disintegrated by the disintegrating chains is conveyed rearwardly along the top runs of the disintegrating chains to discharge onto the conveying means 9, by which the material is conveyed rearwardly along the top of the apparatus to discharge into the hopper-like portion 19 of the delivery conveyor 20. The discharge end of the delivery conveyor may be adjusted to the desired elevation by the cylinder and piston mechanism 244, 245 under the control of the slide valve 263, and the delivery conveyor may be manually swung laterally to the desired discharging position. During the sumping movements of the vein-attacking and disintegrating mechanism, the pusher or shovel 11 moves forwardly therewith to push loose material which has dropped to the mine floor forwardly under the downwardly extending disintegrating mechanism so that the latter's lower chain runs may move the loose material, as it is forced up in a heap or pile and into contact with the disintegrating devices, forward, upward and then rearward and deposit it on the conveyor portion 10. The vein-attacking and disintegrating mechanism, by suitable operation of the swinging cylinders 60 and 61 under the control of the slide valve 264, may be swung in a horizontal direction about the swivel axis of the swiveled frame or turntable 4, to locate the same in different radial positions so that a series of adjacent vertical segments of coal or other mineral may be suitably removed from the working face until the coal or mineral across the entire width of the face has been removed and loaded out. During the sumping, swinging and withdrawing operations of the vein-attacking and disintegrating mechanism, dust allaying liquid may be sprayed on the working face in the zone of action of the disintegrating chains, so that the presence of objectionable and hazardous dust is reduced to a minimum. It may be noted that the rearward end of the shovel 11 is open and directly at the forward end of the conveyor portion 10, so that any material which moves completely through the shovel and reaches the rearwardly traveling flights of the conveyor portion 10 may be moved along rearwardly by the latter. Most of the material, however, does not pass through the shovel, but is rather pushed by the latter

when the same is loaded, forwardly for handling by the disintegrating chains.

As indicated above, my invention in another embodiment thereof from its broader aspects may be incorporated in a form in which, instead of having a fixed discharge point to a laterally swingable discharge conveyor, made possible through the use of a take-up mechanism of the character above described, there may be employed a main conveyor having its rear end—and if desired its driving motor—movable forwardly and rearwardly as the forwardly and downwardly inclined front end of the conveyor is fed forward during sumping and retracted during withdrawal, with the disintegrating apparatus, there being provided a laterally swingable delivery conveyor having a larger, and particularly a longer, material receiving compartment so that it may receive the material discharged from the forward conveyor in all of the discharge positions of the rear end of the latter and in all of its own laterally swung positions; and there may be provided means, for example, as hereinafter disclosed, a master and slave cylinder mechanism, for synchronizing movements of the discharge end of the conveyor with those of the forward end thereof, so that necessary movement may be provided for and proper chain tension may be maintained. Such a modified embodiment of my invention in its broader aspects is illustrated in Figs. 24 to 28, and will now be described.

This embodiment includes a tractor supported base including a stationary frame 2', and this frame, as far rearward as the frame element 26', which corresponds to the frame element 26 of the first illustrative embodiment, is the same as the corresponding frame structure of such first embodiment. Rearwardly of the frame element 26' differences exist, in view of the facts (1) that there is no take-up loop in the lower run of the conveyor chain 45', (2) that the drive sprocket 148' is bodily movable longitudinally of the apparatus like amounts, and in like directions, and at like rates with the front sheave or idler roller 142 (not shown in Figs. 24 to 28), (3) that the conveyor driving motor 16' is supported for bodily movement longitudinally of the apparatus with the drive sprocket 148', and (4) that to receive material from the longitudinally movable delivery end of the forward conveying means there are necessary certain modifications of the tail conveyor 20', as above indicated.

The differences between the embodiments will be described as may be required for a clear disclosure of this illustrative embodiment of the invention, and it will be understood that like parts are identified by like reference characters when they are identical, and by primed like reference characters or by different characters when changes, more or less great, in structure or arrangement exist. It may be said that everything to the right of the line A—A on Figs. 24 and 25 is the same in both of the first two embodiments.

The flight carrying chain 45' is somewhat shorter in this embodiment of my invention, even though its driving sprocket is in fact a greater distance from its forward end, because there is no take-up loop. Its guiding plate 193', which corresponds generally to the upper rear guiding plate 193 of the first embodiment, is shorter because its rear end terminates at such a point as to permit room for the necessary advance of the drive sprocket 148', and associated parts, to compensate for the forward movement of the front idler roller or guide sheave 142. Its lower guide plate 188' does not extend so far back as does the guide or support plate 188, and instead of being joined to a forwardly and upwardly inclined plate portion 49, there is a downwardly sloping forward portion 285 and a still further horizontal portion 286, the latter having its forward end arcuate, as does the plate portion 49, to cooperate with the convexly arcuate rearward portion of the plate 30. A forwardly and downwardly sloping chain guide 287 is provided to cause the lower run of the chain to pass smoothly

into the space between the plates 31 and 44. The lower plate 188' will thus be noted to be differently shaped but to extend forwardly to a like extent with the plate 188, but its rearward end terminates even further forwardly than does the rearward end of the plate 193', and there is provided a transverse support element 288 for the rearward end of the guide plate 188'.

The side frame elements 150' of this embodiment of the invention terminate considerably forward of the position of the rearward ends of the corresponding side frame elements 150 of the embodiment first described, but there are secured to the rearward extremities of the side frame elements 150', as by welding, heavy side plates 291, 291, each including a wide, rearwardly extending, upper plate portion 292 and a lower, narrower, rearward extension 293, the portions 292 and 293 being connected by generally triangular plate portions 294. The lower edges of the portions 292 have guide bars 295 integrally connected with, or welded to, their outer sides.

20 A carriage or sliding frame generally designated 300 is mounted to slide on the guide bars mentioned, and includes a pair of relatively longer inner plates 301, 301 engaging the inner sides of the plate portions 292, and an outer shorter pair of plates 302 having guide portions 303 provided with grooves 304 to receive the guide bars 295. The plates 301 and the plates 302 are suitably rigidly connected together. The carriage or sliding frame also includes upper and lower generally horizontal plate or pan elements 305 and 306, the former forming a 30 relatively slidable continuation of the plate 193' over which the top run of the conveyor chain travels and the latter overlying at its forward end the plate portion 188' which guides the lower run of the chain 45'. The drive sprocket 148' is supported by means of a transverse shaft 308 journaled in suitable bearings 309, 309 mounted on the sliding frame 300, and is driven by the motor 16', through suitable reduction gearing, not shown, housed in a gear casing 310, the motor 16' and the gear casing 310 and its enclosed gearing being supported upon the right hand side of the sliding frame 300, upon a bracket 311 integral with the latter, and in a laterally spaced relation to the adjacent side plate 302 for a reason shortly to be explained. Flexible side boards 290' arranged generally similarly to the side boards 200 of the first embodiment terminate at their rearward ends in overlapping relation with the forward ends of the inner plates 301, 301.

45 In this modified embodiment of the invention, as previously indicated, the sliding carriage 300, which carries the driving sprocket 148' for the conveyor chain 45', the driving motor 16' and the transmission gearing between the motor and the shaft 308 which supports and drives the sprocket 148', is advanced bodily during sumping of the disintegrating apparatus and is moved backwardly during withdrawing movement of the disintegrating apparatus. To effect this cooperative action, a master and slave cylinder arrangement similar to the one described in connection with the first embodiment of the invention is employed. As the disintegrating mechanism is adjusted laterally in order that it may attack the coal vein or seam at different points across a face, there is a necessity, in order that the chain tension may be maintained the same in the conveyor, for a bodily adjustment of a few inches of the drive sprocket 148'. 50 In order, therefore, to take care of the adjustments of the drive sprocket 148' necessary to compensate for the lateral swinging of the forward end of the conveyor chain 45' and to provide for the bodily movements of substantial length—a length equal to the movement, during sumping, of the front idler roller 142, an arrangement generally similar to that employed in the first embodiment of the invention is used. In this case, however, the thrust bar 212' actuated rearwardly by the cam 210 55 is somewhat longer, and it is connected to a transverse

frame element 163', which has a tongue 315 which enters a central opening 316 in the thrust bar 212' and is fixed to the latter. The transverse frame element 163' is guided in guideways 164' in the side frames 150', and is connected at 317 between ears 318 carried by the rear heads of the slave cylinders 162' by means of tongue portions 319 formed at the outer ends of the transverse frame element 163'. The slave cylinders contain pistons 161' and have rearwardly extending piston rods 160' which are connected to collars 320 surrounding cylindrical bosses 321 extending outwardly from the forward ends of the plates 302 of the sliding frame 300. Accordingly, since the slave cylinders 162' are filled with fluid at both sides of their pistons 161', any adjustments of the transverse frame element 163' occasioned by movements of the cam 210 as the disintegrating mechanism is adjusted laterally in a manner to occasion rearward movement of the transverse frame element 163' will be transmitted to the slave cylinders 162' and through the liquid which they contain and, through their pistons 161' and piston rods 160' and the collars 320 and bosses 321 previously mentioned, to the sliding frame 300. Moreover, any movements of the pistons of the slave cylinders caused by displacement of the fluid in the slave cylinders by movements of the piston 222 in the forward master cylinder 220 (shown in the first embodiment) as sumping and withdrawing takes place, will be transmitted to the sliding carriage or frame 300, and accordingly, as the disintegrating mechanism is moved forwardly to sump it into the vein or coal seam, there will be a corresponding and equal forward movement of the drive sprocket 148', and as the disintegrated mechanism is moved rearwardly to effect its withdrawal the sprocket 148' will be moved rearwardly a corresponding amount and thus maintain the tension of the chain 45' uniform.

In contrast to the first described embodiment of the invention, it will be observed that, instead of the reciprocation of an idler in a take-up loop, there is reciprocation of a sliding carriage 300, including slide plates 301, 301 and 302, 302, the latter providing supports for the shaft 308 which carries the sprocket 148' and further including upper and lower plates 305 and 306 which slide between the upper and lower plate portions 193' and 188' which provide supports for the chain 45' in its upper and lower runs respectively.

The lower extensions 293 of the rearward frames or frame extensions are connected by a suitable platform arrangement 333 on which there is supported for rotation on a vertical axis a pivotal support 334 which provides upstanding ears 335 receiving stub shafts or bosses 336 extending laterally from the side frames of the delivery conveyor 20'. This conveyor 20' has a guide sprocket 337 supported on a transverse shaft 338 journaled in a partial housing 339 at the forward end of the conveyor 20' and a suitable conveyor element 340 passes about this sprocket and rearwardly over a guide frame 341, as shown in Fig. 24. It may be noted that the receiving end 342 of this conveyor extends forward, when the parts are in the position indicated in Fig. 24, to such an extent that the discharge end of the conveyor chain 45' is well rearward of the pivot support for the delivery conveyor, and when the delivery end of the conveyor chain 45' advances, as occurs during sumping of the disintegrating mechanism, there will still be such an overlap of the rearward end of the chain 45' with the conveyor 20' that there will still be an effective delivery of all of the material carried back by the conveyor chain 45', onto the delivery conveyor 20'. Therefore, there is present in this second embodiment of the invention a main conveyor chain 45' whose full length, as it were, advances and retracts as a unit, and which takes the material from the disintegrating mechanism and conveys it back and deposits it in various positions upon a delivery conveyor which underlies, at all points of dis-

charge of the main conveyor, the discharge end of that conveyor. There is no lateral adjustment—merely a longitudinal movement—of the delivery end of the main conveyor mechanism, and the receiving conveyor 20' is so constructed that it will underlie and receive within its borders the material delivered by the primary conveyor, notwithstanding the angular adjustments of the receiving portion of the receiving conveyor 20' as the latter is raised and lowered at its delivery end and as its delivery end is moved laterally in one direction or another as may be needed to effect final delivery of the disintegrated material at a desired point. The adjustable connections for the conveyor 20' are similar to those of the conveyor 20 of the first embodiment, and are pivotally supported at their forward end on a cross bar 344 extending between the top of the rearward ends of the side plate portions 292. As the mode of operation of this modified embodiment is similar to that above described, a description of the mode of operation of this form of the apparatus is unnecessary.

The modified embodiment shown in Figs. 29 to 65 inclusive is incorporated in an apparatus which in many of its features is the invention of said John R. Sibley above mentioned, and which is disclosed and claimed 25 as to the inventions of said Sibley therein disclosed, in the above mentioned Sibley application. The continuous mining apparatus of this embodiment generally comprises a mobile base 401, herein preferably a tractor or crawler base, having a frame 402 which has swiveled thereon at 403, to swing about an upright axis in horizontal planes with respect thereto, a horizontal supporting frame or turntable 404. The swiveled supporting frame or turntable has a horizontal portion 405 projecting forwardly in advance of the base 401, and guided 30 on this horizontal frame portion for movement rectilinearly relative thereto in a radial direction relative to the swivel axis is a sliding frame or support 406, on which a swingable frame or bar structure 407 is pivotally mounted on a horizontal transverse axis to swing in vertical planes with respect thereto and to swing horizontally with the swiveled supporting frame or turntable 404 relative to the base 401. The vertically swingable frame or bar structure 407 extends forwardly in advance of the swiveled frame, with its pivotal axis located, 35 when the sliding frame 406 is retracted, a substantial distance in advance of the base. The swingable frame structure 407 carries a mine vein-attacking and disintegrating mechanism generally designated 408, similar to the vein-attacking and disintegrating mechanism 8 of the embodiments above described, for detaching and disintegrating the coal or similar mineral in vertical segments from a solid coal seam or mine vein. The vein-attacking and disintegrating mechanism 408, when disposed in a horizontal position as shown in Fig. 30, has 40 its upper limits disposed below the upper limits of the apparatus, thereby resulting in a construction which is extremely vertically compact. Arranged substantially coaxially with the swivel of the horizontally swinging frame is a receiving and collecting means, preferably in 45 the form of a hopper 409, which is mounted in stationary relation with respect to the base frame; and conveying means is provided for conveying material to the hopper and for discharging material from the hopper including a front receiving conveyor portion and a rear discharging conveyor portion. The front conveyor portion comprises 50 a front loading conveyor 410, carried by the sliding frame 406, serves to convey the disintegrated coal or other mineral discharged from the vein-attacking and disintegrating mechanism rearwardly of the sliding frame to the hopper. The rear conveyor portion is mounted on 55 the base frame and comprises a rear discharge conveyor 411 which has its receiving end projecting downwardly within the hopper for moving the disintegrated coal or other mineral from the hopper rearwardly of the apparatus to a suitable point of delivery remote from the vein-

attacking and disintegrating mechanism. The rear discharge end of the front conveyor overlies the hopper and is so arranged that it discharges into the hopper in all positions of the sliding frame with respect to the horizontally swiveled frame. The vein-attacking and disintegrating mechanism 408 detaches the coal or other mineral from the coal seam or mine vein, and as the mineral is detached or torn away toward the free face of the vein or seam, it is moved by the vein-attacking and disintegrating mechanism rearwardly along the top thereof to discharge onto the front conveyor 410, which in turn discharges into the hopper 409; and the disintegrated coal or other mineral is discharged from the hopper and conveyed rearwardly of the apparatus by the rear discharge conveyor. Carried by the sliding frame 406 beneath the rearward portion of the vein-attacking and disintegrating mechanism is a pusher element or shovel 412 for moving loose coal or mineral which has fallen to the mine floor into position for loading by the vein-attacking and disintegrating mechanism.

A pair of motors 413, 413, preferably electric motors, carried by the swiveled supporting frame or turntable 404 at the opposite sides of the hopper, serve to drive the vein-attacking and disintegrating mechanism 408, and one of these motors drives the front conveyor 410; a pair of reversible motors 414, 414, preferably electric motors, individually drive endless crawler treads 415, 415 of the tractor base; and a pair of motors 416, 416, preferably electric motors, drive the rear discharge conveyor 411. A motor 417, likewise preferably an electric motor, drives a pumping means 418 for delivering liquid under pressure to the various hydraulically operated devices of the apparatus. The crawler treads 415 of the tractor base serve to propel the apparatus about the mine and to steer the apparatus. By swinging the vein-attacking and disintegrating mechanism 408 about the swivel axis of the supporting frame or turntable 404, it may be located in different radial positions relative to the base to attack and disintegrate the coal seam or mine vein in a series of vertical segments of the working face so that the entire width of the working face may be dislodged and disintegrated in successive steps, and the front conveyor is arranged to discharge into the hopper in all radially adjusted positions of the vein-attacking and disintegrating mechanism.

The frame 402 of the tractor or crawler base 401 has an annular portion 420 arranged in a low position between the tractor treads and providing an open center and having an inwardly directed circular flange 421. Arranged within the open center of the annular frame are front and rear transverse brackets 422 and 423 rigidly secured by horizontal webs to the annular portion 420, and the hopper 409 is arranged centrally of the annular frame and is supported by and secured to the transverse brackets in the manner shown in Fig. 42. Thus, the hopper is rigidly supported in a stationary position on the base frame. The circular flange 421 supports bearings on which an annular portion 424 of the swiveled supporting frame or turntable 404 is rotatably mounted, and this annular portion surrounds the hopper in the manner shown. A segmental retaining ring 425, secured as by screws to the annular portion 424, serves to retain the swiveled supporting frame on its bearing mounting. The lower portion or closed bottom of the hopper 409 projects downwardly within the open center of the annular frame below the bottom surface of the retaining ring 425, thereby to provide an extremely low compact construction.

For turning the swiveled supporting frame or turntable 404 on its swivel mounting, there are arranged transversely of the base frame rearwardly of the turntable mounting parallel, double acting, horizontal hydraulic cylinders 428, 428 rigidly secured together and containing stationary pistons 429, 429 relative to which the cylinders are reciprocable. The pistons have oppositely

extending piston rods 430 extending outwardly through the packed heads 431 of the cylinders and rigidly secured to 432 to side portions 433 of the base frame. The piston rods are made hollow and have fluid pipes, hereinafter described, connected thereto for supplying liquid under pressure through the piston rods and through ports 434 at the opposite sides of the pistons to the opposite ends of the cylinders. Arranged vertically between the cylinders and spaced equi-distantly from the longitudinal center of the cylinders are non-rotating shafts 435 which support bearings 436 on which horizontal rollers 437, 437 are journaled. Arranged symmetrically at opposite sides of the base frame and journaled on vertical axes on horizontal portions 438 of the frame are pairs of rollers 439 and 440. Passing around the sets of rollers 437, 439 and 440, at opposite sides of the base, are chain sections 441, 441 (Fig. 54), each being yieldably connected at one end as by springs 442 to the side of the base. These springs are each arranged 10 within sleeve-like housings 443 secured to the base frame and having end caps 444 against which the inner ends of the springs react. Secured to the chain sections are plungers 445 having outer heads 446 engaging the outer ends of the springs. The opposite ends of 15 the chain sections are secured at 447 to an abutment member 448, in turn secured as by screws within a slot 449 at the central portion of the swingable supporting frame 404. The springs 442 serve to maintain the chain sections under tension. When liquid under pressure is supplied to one end or the other of the cylinders, the latter are moved axially relative to the pistons to reduce the effective length of one chain section while increasing the effective length of the other, thereby causing the swingable supporting frame 404 to be turned in one direction or the other on its swivel mounting. When liquid is trapped within the opposite ends of the cylinders at opposite sides of the pistons, the swiveled supporting frame is locked in adjusted position. The means for supplying liquid under pressure to the fluid pipes connected to the piston rods for supplying fluid under pressure to the cylinders will later be described.

The specific form of turntable mounting, hopper, and means for swinging the frame horizontally incorporated in this embodiment of my broad invention are specifically 20 25 30 35 40 45 50 55 60 65 70 sliding surfaces of the guideways, as shown in Fig. 48. Replaceable wear plates 464 are arranged between the upper surface of the rear guide portion and the upper surface of the guideway and extend downwardly along the inner edges of the guides.

Improved hydraulic means is provided for reciprocating the sliding frame or support 406, which includes, arranged longitudinally along the inner sides of the parallel side frame portions 451 of the swiveled supporting frame or turntable 404, double acting, hydraulic feed cylinders 466, 466 having lugs integral with their rear heads 467 pivotally connected to transverse pivot pins 468 secured in bores in the side portions 451. Reciprocable in these cylinders are pistons 469 having piston rods 470 extending forwardly through the front packed cylinder heads 471. The front ends of the piston rods have lugs pivotally connected to transverse pivot pins 472 secured in bores in lateral brackets 473 integral with the sliding frame or support 406. When liquid under pressure is supplied to one end or the other of the cylinders 466, the pistons 469 may be moved to feed the sliding frame 406 rectilinearly back and forth along the guideways 455. By trapping liquid in the feed cylinders, the pistons may be locked in position to hold the sliding frame against sliding movement. The means for supplying liquid under pressure to the cylinders 466 will later be described.

Various means may be provided for swinging the frame structure 407 which carries the vein-attacking and disintegrating mechanism 408, as has already been demonstrated, and as a desirable means for this purpose in the present embodiment of the broad invention there is shown a specific structure which is described and claimed in the above mentioned Sibley application and which comprises a pair of single acting hydraulic cylinders 475 (see Figs. 30, 38 and 43) having upstanding lugs 476 at their upper sides secured, as by bolts, to depending lugs 477 integral with the spaced front side portions 478 of the sliding frame 406. The cylinders are arranged in parallel relation at the outer sides of the pusher element or shovel 412, as shown in Fig. 38, with their axes inclined slightly upwardly and forwardly, and reciprocable in these cylinders are pistons 479. The pistons are pivotally connected to pitmen 480 which extend forwardly outwardly through the open front ends of the cylinders, and the front ends of the pitmen are pivotally connected at 481 to rearwardly curved depending arms 482 secured to the outer sides of the swingable frame structure 407. When liquid under pressure is supplied to the rear ends of the cylinders 475, the pistons 479 are moved forwardly to swing the frame or bar structure 407, together with the vein-attacking and disintegrating mechanism 408 carried thereby, upwardly about its pivot. By trapping liquid in the cylinders, the frame structure may be locked in adjusted position, and upon appropriate venting of liquid from the cylinders, the frame structure may be permitted to swing downwardly about its pivot at a controlled rate. The means for supplying liquid under pressure to and venting liquid from the cylinders will later be described.

The vein-attacking and disintegrating mechanism 408, as above stated, is similar to the other embodiments and similarly comprises a series of endless disintegrating chains 485 guided in parallel guideways 486 for circulation in vertical orbital paths. Each chain comprises a series of chain blocks 487 pivotally connected by intermediate strap links 488 which are pivotally connected to the blocks by hinge pins 489. The blocks have lateral gibs 490 at their bases received in the guideways, and projecting laterally from the blocks are lugs 491 which has sockets for receiving disintegrating elements, herein in the form of cutter bits 492, held in position on the lugs by conventional set screws 493. The disintegrating bits on the chains may be arranged in various manners but are desirably arranged with the bits set in straight transverse rows, preferably with alternate rows inclined laterally at opposite angles, in the manner shown. Evidently, the

bits may be staggered in various manners as desired. It will be noted, however, that six chains are shown for purposes of illustration, that the corresponding bits in each chain are similarly disposed, that the bits are arranged in rows perpendicular to the planes of their orbital movement, and that most of the bits have their tips, as they pass along the plane portions of their orbits, in a common plane. The frame or bar structure 407 has an adjustable outer end portion or bar idler head having side plates 494 which, at their outer sides, desirably lie flush with side plates 495 of the rearward frame portion. The side plates of the adjustable outer portion are provided, at the sides thereof, with rearward guides 496 received in longitudinal guiding slots 497 in the sides of the rearward side plates 495. The guides 496 have longitudinal slots 498 which are engaged by retaining blocks 499 secured, as by screws, to the forward ends of the side plates 495 of the rearward portion of the frame structure. The adjustable front end portion has parallel tubular elements 500 secured to the adjustable outer end portion and slidably received in parallel longitudinal tubular guides 501 secured to transverse plates 502 which rigidly brace the forward ends of the side plates 495 of the rearward frame portion. The tubular guides 501 are preferably welded to the transverse plates 502 and have parallel bores in which the tubular guides 500 are received. The tubular guides 500 have nuts 503 engaged by adjusting screws 504, and the screws have collars 505 engaging inwardly directed flanges 506 on the rearward ends of the tubular guides 501. The screws have polygonal portions 507 which are accessible through side openings 508 in the side plates 495 and are engageable by a suitable turning instrument, such as a wrench. Supported within end supports 510 secured to the side frames 494 of the bar idler head is a transverse shaft 511 which supports bearings 512 on which an elongated idler roll 513 is journaled. The endless disintegrating chains are guided by the idler roll 513 as they pass around the outer end of the swingable bar structure 407. Thus, by suitably adjusting the screws 504, the adjustable frame portion or bar idler head may be adjusted radially outwardly along its guides relative to the rear frame portion to vary the tension of the chains. The swingable bar structure comprises parallel upper and lower transverse plates 515, 516 held in spaced relation by at least one perpendicular transverse bracing plate, 517, and front plates 502. The transverse bracing plates may be welded to the upper and lower plates 515 and 516 to provide a rigid unitary structure. Secured likewise as by welding, to the outer surface of the upper and lower plates are outer plates 518 and 519, the latter being of substantially less length than the former, as shown in Fig. 33. There are herein preferably six chain guideways, and secured to the upper outer plate 518 are parallel, longitudinally extending guide plates 520. Secured to the outer bottom plate 519 are bottom guide plates 521 which are spaced from the bottom plate by wedge-shaped strips 522. These guide plates and strips are secured to the outer plates by bolts 523 passing through the frame structure. These guide plates and strips cooperate to provide the guideways for the gibs on the block bases of the chains. The wedge-shaped strips 522 provide tapered bottom guideways having wide rear mouths for receiving the gibs on the bottom runs of the chains, for a purpose to be later explained. The side frames 494 and 495 of the swingable bar structure have upstanding side portions 524 and 525 which serve to retain the disintegrated material in the paths of the chains. The improved driving connections between the motors 413 and the disintegrating chains comprises a transverse drive shaft 528 coaxial with the frame pivot and suitably journaled in bearings 529 supported in brackets 530 secured to the side portions 478 of the sliding frame 406. Keyed to this shaft 528 is a series of chain sprockets 531 which engage and drive the endless disintegrating chains. Also keyed to the shaft 528 between the chain sprockets

there are impeller elements 532 having radial arms 533 projecting outwardly beyond the sprocket teeth, in the manner disclosed in the Sibley application, for ejecting the disintegrated material from between the chains as the latter travel around the chain sprockets. As the disintegrating chains move forwardly beneath the sprockets, the gibs on the block bases enter the widened mouths of the tapered, lower guides to direct the lower chain runs forwardly and, with the bar frame horizontal or upwardly inclined, upwardly toward the bar frame so that undue sagging of the lower chain runs is prevented. The short bottom guides provide an open space or gap 534 which the bottom chain runs traverse as they travel toward the outer end of the bar frame, thereby to permit any dirt to drop down by gravity from the chains. Each motor 413 has a horizontal tubular motor shaft 535 (see Figs. 34 and 53) journaled in bearings 536 supported within the motor heads, and secured to the rear end of the tubular shaft is a housing element 537 for a multiple disc clutch 538, which is set at a predetermined load by coil springs 539. The interleaved clutch discs are secured to the clutch housing and to an outer member 540 of a universal coupling 541. This universal coupling has its inner elements 542 keyed to a drive shaft 543 which extends forwardly into the tubular motor shaft, as shown in Fig. 53. The shaft 543 has a splined connection at 544 within a tubular shaft 545, also arranged within the motor shaft and keyed at its forward end to an inner element 546 of a universal coupling 547 similar to the coupling 541. Secured to the outer element 548 of this coupling is a shaft 549 suitably journaled in bearings 550 supported within detachable gear housings 551 forming portions of the spaced side portions 478 of the sliding frame 406. Keyed to each shaft 549 is a spur gear 552 meshing with a large spur gear 553 which is keyed to a longitudinal shaft 554, likewise suitably journaled within bearings supported within the gear housing. Fixed to each of the shafts 554 is a worm 555 meshing with and driving a worm wheel 556 having its hub 557 suitably journaled on bearings 558 supported by a transverse shaft 559, the latter in turn being supported within the gear housing. Integral with each of the gear hubs 557 is a spur gear 560 meshing with a large spur gear 561 which is keyed to the adjacent end of the transverse shaft 528. Thus, the shaft 528 is driven at both ends, and as the sliding frame 406 is moved along its guideways, the drives between the motors 413 and the opposite ends of the shaft 528 are maintained through the self-adjusting telescopic shaft connections. By arranging the motors 413 at opposite sides of the turntable frame 404, a low compact, symmetrical and well balanced design is attained.

The front loading conveyor 410 will now be described. This short front loading conveyor and its specific drive and its relation to the hopper also form the subject matter of claims in the aforesaid Sibley application. Guided in guideways provided by a troughlike frame 565 on the sliding frame 406 are endless side chains 566 having transverse flight bars 567 secured thereto for moving the disintegrated material along a top plate 568 secured to vertical side frames 569 secured to the sliding frame. The conveyor chains at the front receiving end of the conveyor pass around front idler rollers 570 secured to a transverse shaft 571 suitably journaled in bearings 572 supported by brackets 573 secured to the side plates 569. The conveyor chains, at the rear discharge end of the conveyor, pass around drive sprockets 575 (see Fig. 45) secured to a tubular shaft 576. This shaft is supported by alined end shafts 577 which have polygonal portions 578 received in correspondingly shaped openings or sockets 579 in the sprocket hubs and these end shafts are suitably journaled in bearings 580A, 580B respectively supported by brackets 581A, 591B attached to the vertical side frames 569. The front receiving end of the front conveyor extends forwardly and downwardly beneath the rear end of the vein-attacking and disintegrating mech-

anism, as shown in Fig. 33. The rear end at all times overlies the top of the hopper 409, in positions in each of which the conveyor may discharge disintegrated material into the hopper.

5 The driving means shown for the front loading conveyor 410 comprises an adjustable-flange pulley 585 (Fig. 53) secured to one of the front universal couplings 547 driven by one of the motors 413, and this pulley is connected by an endless V-belt 586 to a pulley 587 (see 10 Figs. 35, 36 and 37). The pulley 587 has its hub 588 keyed to a longitudinal shaft 589 suitably journaled in bearings 590 supported within a bearing bracket 591 attached to the adjacent side portion 478 of the sliding frame 406. The shaft 589 drives, through a universal 15 joint 592, a shaft 593 which extends rearwardly along the outer side of the frame of the front conveyor between the latter and the adjacent motor 413, as shown in Fig. 29. The rearward portion of the shaft 593 is splined at 594 to a tubular element 595 of a universal 20 joint 596. The universal joint has an element 597 keyed to a longitudinal shaft 598 suitably journaled in bearings 599 supported within a gear housing 600 attached to the rearward portion of the adjacent side frame 569 of the front conveyor. Secured to this shaft is a worm 601 meshing with and driving a worm wheel 602 secured to the projecting end of the end shaft 577 which drives the chain drive sprocket 575. Thus, the front conveyor 410 is driven through the self-adjusting telescopic shaft connection driven by one of the motors 413 which drives 25 the vein-attacking and disintegrating mechanism. The gear housing 600 is adjustable longitudinally relative to the conveyor frame by set screws 603 engaging lugs on the housings, and the housings have slots with which 30 clamping screws 604 cooperate for securing the housings in adjusted position. By adjusting the housings, the tension of the conveyor chain may be varied as desired. 35

The pusher or shovel 412 has rearward side frame portions 605 (Fig. 38) arranged between the vertical side frames 569 of the front conveyor 410 and the front idler rolls 570. These shovel side portions engage bearings 606 supported by the bearing brackets 573. Thus, the shovel may swing in vertical planes about an axis coincident with the axis of the front idler shaft 571 of the front conveyor. The shovel has a widened forward end, as shown in Fig. 38, provided with a front edge 607 which is disposable in contact with the mine floor. Pivotally mounted at 609 between depending lugs 610 integral with the forward portions of the sliding frame 406 is a single acting hydraulic cylinder 611, as shown 45 in Fig. 41. This cylinder contains a reciprocable piston 612 having a piston rod 613 extending downward through the lower packed cylinder head 614. The piston rod is pivotally connected at 615 to ears on the rearward portion of the shovel or pusher at a point to the rear of the latter's pivot, as shown in Fig. 41. The upper cylinder head 616 is pivotally connected to the sliding frame 406. When liquid under pressure is supplied to the upper end of the cylinder, the piston is moved downward to swing the shovel or pusher upward about its pivot to lift the front edge of the shovel or pusher from the floor. The 50 means for supplying liquid under pressure to the shovel or pusher lift cylinder will later be described.

As shown and claimed in the Sibley application mentioned above, the forward side portions 478 of the sliding frame are transversely braced by a transverse tubular brace member 622, and formed integral with this brace member is a forwardly and upwardly inclined stripper or so-called "scalper" 623 of V-shape in cross section, preferably composed of welded strips. This 55 stripper member serves to deflect the disintegrated material from the paths of the disintegrating chains and to direct the material toward the front conveyor. Any material which drops beneath the disintegrating chains forwardly of the stripper is received by the gathering head 60 412.

It will be noted that the hopper 409 has an upwardly inclined rearward trough-like portion 625, and projecting horizontally and rearwardly from this inclined portion is a vertically tiltable rearward troughlike frame portion 626 which is pivoted on a transverse horizontal axis at 627. Pivoted at 628 on the rearward portion of the frame portion 626 is a laterally swingable rearward frame portion 629, likewise of troughlike form. Circulated in guideways on the frame portions 623, 626 and 629 is a flight conveyor of the universal type comprising a centrally located universal drive chain 630 having a plurality of laterally extending flights 631 thereon. The front receiving end of the rear conveyor extends downwardly within the hopper 409, as shown in Fig. 42, and the conveyor chain passes around a front idler sprocket 632 (see also Fig. 45) secured to a transverse shaft 633. End shafts 634 alined with the shaft 633 have polygonal portions 635 received in correspondingly shaped openings or sockets 636 in the ends of the shaft 633, and the end shafts are journaled in bearings 637 supported within brackets 638 secured to the sides of the hopper. The conveyor chain, at the rear discharge end of the conveyor, passes around a rear drive sprocket 640 secured to a transverse shaft 641. The shaft 641 is supported in a manner similar to the shaft 633 and has end shafts 642 journaled within a rear bearing bracket 643. This bearing bracket is slidably guided in longitudinal guideways 644 on the rearward portion of the rear conveyor frame 629, and abutment screws 645 carried by the bracket are provided for adjusting the position of the bearing bracket relative to adjusting means therefor later described. Secured to the opposite sides of the rearward conveyor frame portion 629 are the motors 416 which have their power shafts connected through conventional speed reducing gearings, not shown, to longitudinal shafts 647. Shafts 647 are connected through universal joints 648 to tubular shafts 649 splined at 650 to shafts 651. The rear ends of the shafts 651 are connected through universal joints 652 to shafts 653 suitably journaled within gear housings 654 attached to the opposite sides of the adjustable bearing bracket 643. Secured to the shafts 653 are worms 655 meshing with worm wheels 656 secured to the end shafts 642 which drive the drive sprocket shaft 641. For tilting the rearward portion of the discharge conveyor in a vertical direction about the pivot 627, there is a single acting hydraulic cylinder 660 pivotally mounted at 661 on a transverse tubular pivot rod 662 secured to the sides of the base frame. Reciprocable in this cylinder is a piston 663 having its hollow piston rod 664 extending upwardly through the upper packed cylinder head 665. The upper end of the piston rod is pivotally connected at 666 to a pivot rod secured to the tiltable frame portion. Thus, when liquid under pressure is supplied to the lower end of the cylinder beneath the piston, the rearward portion of the rear conveyor may be tilted in a vertical direction, and when liquid is vented from the cylinder, the rear discharge end of the conveyor may be lowered at a controlled rate. The means for supplying liquid under pressure to and for venting liquid from the conveyor tilt cylinder will later be described.

Now referring to the means for swinging the rearward portion of the rear discharge conveyor in horizontal planes, it will be observed that secured to the rearward portion of the conveyor frame portion 626 are upper and lower transverse frame members 670 and 671 secured, as by welding, in rigid spaced relation. Secured to these frame members are pivot supporting members 672 and 673 which receive tubular pivot elements 674 and 675, arranged in vertical alinement and the former rotatable and the latter non-rotatable with respect to its associated supporting members. Secured to the horizontally swingable rear conveyor frame portion 629 are elements 676 and 677, the former rotatable with the pivot element 674 and the latter pivotal about the pivot

element 675. Single acting hydraulic cylinders 680, 680, spaced equi-distantly from the opposite sides of the pivot 628 are shown in Fig. 61, have lugs 681 secured to the rear cylinder heads pivotally mounted on vertical pivots at 682 on brackets 683 secured to the transverse frame member 671. Reciprocable in these cylinders are pistons 684 having piston rods 685 projecting rearwardly through the packed rear cylinder heads 686, and the piston rods are pivotally secured, by vertical pivots at 687, to projections 688 secured to a transverse plate 689 secured, as by welding, to the horizontally swingable conveyor frame portion. Thus, when liquid under pressure is supplied to one or the other of the cylinders 680, the rear portion of the rear conveyor may be swung horizontally about the pivot 628 in one direction or the other, and when liquid is trapped in the cylinders, the conveyor may be locked in adjusted position. The means for supplying liquid under pressure to the conveyor swinging cylinders will later be described.

For the purpose of guiding the upper run of the flight conveyor during the lateral swing of the rearward discharge end of the conveyor, flexible side members 692 are provided. These flexible side members are secured to the upstanding sides of the conveyor frame portion 626 and extend along the inner surfaces of the upstanding sides and are guided at their rearward portions in guides on the upstanding sides of the rear conveyor frame portion 629. These guides comprise guiding elements 693 secured to the flexible side members, and are slidably engaged in longitudinal slots 694 in the side members of the frame portion 629 (see Figs. 32 and 60). Thus, when the rear discharge end of the rear conveyor is swung laterally, the flexible side members are flexed to provide guide surfaces for the ends of the flights of the conveyor chain and serve to direct the material being conveyed therebetween. The flight conveyor moves the material rearwardly over the bottom plates 695, 696 and 697 of the conveyor frame portions 625, 626 and 629, likewise in the manner fully disclosed in my application, Serial No. 783,759. A cam 700 (Figs. 58 and 62) on the conveyor frame portion 626 is engaged by a roller 701 carried by a sliding bar 702, guided on the rearward frame portion 629 and secured, at its rear end, to a plate 703, in turn secured to the adjustable bearing bracket 643. The screws 645 may be used to effect close adjustments between the bracket 643 and the plate 703. As the rearward portion of the rear conveyor is swung horizontally out of central position, the sliding bar 702 will be adjusted longitudinally by the roller engaging the cam to move the bearing bracket along its guideways to maintain the conveyor chain under the desired tension in all of its angular positions of lateral adjustment. Thus, as the rear discharge end of the rear conveyor is swung horizontally, there will be an automatic maintenance of proper chain tension, thereby preventing the introduction of slack into the flight conveyor chain, which would otherwise occur due to the lateral displacement of the conveyor chain with respect to the pivot 628 as the conveyor is swung horizontally. The self-adjusting telescopic drive shaft connections between the motors 416 and the chain drive sprocket 640 maintain the conveyor drive in all positions of lateral and vertical adjustment thereof.

Suitable driving connections are provided between the motors 414 and the crawler treads 415 to enable the propulsion and steering of the apparatus. As such drives may assume many forms, and as the drive is not per se claimed in this application, and as the drive used in the apparatus which is illustrated to show a third embodiment of the invention is, specifically, the invention of Sibley and fully described and claimed in the Sibley application above referred to, further disclosure and description thereof is herein unnecessary, though it may be stated that the motors 414 may be independently controlled to effect propulsion and steering of the apparatus

during tramping from one working place to another about the mine.

As the vein-attacking and disintegrating mechanism is operated to effect dislodgment of the coal or other mineral, a dust allaying liquid, such as water, may be sprayed in the vicinity of the zone of action of the disintegrating chains to reduce the dust hazard. Such dust allaying means may assume various forms, but is herein similar to the one shown and claimed in the above mentioned application of John R. Sibley. The spray liquid conducting means comprises a water pipe 745 (Fig. 33) extending longitudinally within the swinging frame or bar structure 407, on which the disintegrating chains are guided, and this water pipe communicates with a transverse chamber 746 formed in the adjustable bar idler head at the outer end of the frame structure 407. The water chamber 746 is connected through one or more relatively restricted passages 747, with laterally spaced recesses 748 formed in the outer portion of the idler frame between the chain guideways, as shown in Fig. 52. Each of the recesses 748 has spaced jets 749 through which water under pressure is sprayed outwardly between the disintegrating chains to allay the dust created by the disintegrating elements during the dislodging and disintegrating operation.

Now referring to the hydraulic fluid system and the associated control means of this modified embodiment, it will be noted that the shaft of the motor 417 drives a pulley 750 connected through a multiple V-belt drive 751 to a pulley 752 secured to the drive shaft of the pumping means 418. As shown diagrammatically in Fig. 63, the suction side of the pumping means 418 is connected through a conduit 754 to a liquid reservoir or tank 755. The discharge side of the pumping means is connected through a conduit 756 to the supply passage of a conventional valve mechanism 757. The discharge passage of the valve box is connected through a return conduit 758 back to the tank. The valve box is made up of a series of valve block sections 759 and end sections 760 and 761, and these sections are suitably secured in assembled relation. The end section 760 has an inlet chamber formed therein, while the end section 761 provides the discharge chamber, and the conduit 756 is connected to the inlet chamber and the conduit 758 is connected to the discharge chamber. Associated with the inlet section 760 is a conventional relief valve 762 for connecting the inlet chamber to the discharge passage in the event of overload in the system. The valve block sections 759 have bores containing conventional slide valves of the balanced spool type, respectively designated 763, 764, 765, 766, 767 and 768. The bore containing the slide valve 763 is connected by a conduit 770 to the lower end of the tilt cylinder 660 for the rearward portion of the rear discharge conveyor 411. The bore containing the slide valve 764 is connected through conduits 771 and 772 to the forward ends of the cylinders 680, which effect horizontal swinging of the rearward portion of the rear discharge conveyor. The bore containing the slide valve 765 is connected by a conduit 773 to the head end of the tilt cylinder 611 for the pusher element or shovel 412. The bore containing the slide valve 766 is connected through conduits 774 and 775 to the opposite ends of the transverse cylinders 428 for swinging the swiveled supporting frame or turntable 404 about its swivel axis. The bore containing the slide valve 767 is connected through a conduit 776 to the rearward ends of the swinging cylinders 475 for the vein-attacking and disintegrating mechanism 408. A conventional relief valve 777, set to open at a predetermined pressure in the elevating cylinders, is connected by a conduit 778 to the return conduit 758 so that the swing cylinders are connected to exhaust in the event of excessive pressures therein. The bore containing the slide valve 768 is connected through conduits 779 and 780 to the opposite ends of the feed cylinders 466 for feeding the pusher or shovel and the vein-attacking and disintegrating mechanism back and

forth along the guideways on the swiveled supporting frame or turntable. The several mechanisms are arranged so that when all of the control valves are in their "off" positions there is a free flow from the conduit 756 to the conduit 758; that when any valve is moved to supply or "on" position, such free flow is interrupted.

The electrical control apparatus for the several electric motors 413, 414, 416 and 417 comprises an electrical control box 785, to which leads a usual power conductor cable. This control box is arranged at the rear end of the base frame at the left hand side of the apparatus, as shown in Fig. 31. At the rear end of the base, at the right hand side of the apparatus as shown in Figs. 31 and 32, is a starting switch box 786 containing switches having control handles 787 and 788 for controlling the tread driving motors 414. Push button starting switches 789 and 790 are provided for controlling the motors 413, 416 and 417.

The general mode of operation of this embodiment 20 of the improved mining and loading apparatus is as follows: The apparatus may be propelled about the mine and steered by the motors 414 for driving the crawler treads 415 and controlled by the switch levers 787 and 788. When the apparatus assumes the position adjacent 25 the working face of the coal seam or mine vein, as shown in Figs. 64 and 65, the pump driving motor 417 may be operated to cause the pumping means 418 to build up a pressure in the hydraulic system, and liquid under pressure may be supplied to the transverse swing cylinders 30 428 under the control of the slide valve 766 to effect swinging of the vein-attacking and disintegrating mechanism 408 laterally to the right, into the position indicated in dotted lines at A in Fig. 64. The slide valve 767, controlling liquid flow with respect to the swing cylinders 475, may be positioned to discharge fluid from the cylinders 475 to cause the vein-attacking and disintegrating mechanism to swing downwardly until its outer end portion assumes a position near the level of the mine floor, as indicated in dotted lines at B in Fig. 65. The motor 35 control switches may then be manipulated to effect running of the motors 413 and 416 to effect circulation of the endless disintegrating chains and the conveyor chains within their guideways. The slide valve 765 may then be positioned to effect downward swinging of the gathering shovel or pusher 412 to bring its front edge into 40 contact with the mine floor. The slide valve 768, controlling liquid flow with respect to the feed cylinders 466, may then be positioned to supply liquid under pressure to the rear ends of the cylinders to effect forward feeding movement of the vein-attacking and disintegrating mechanism to sump the outer portion thereof into the coal or mineral vein, forwardly to the position indicated in dotted lines at C in Figs. 64 and 65. When the outer portion of the vein-attacking and disintegrating mechanism has been sumped into the coal, liquid may be 45 trapped in the feed cylinders 466 to hold the sliding frame 406 in its advanced position, and the slide valve 767 may be positioned to supply liquid under pressure to the rear ends of the up-swing cylinders 475 to effect upward swinging of the vein-attacking and disintegrating mechanism, 50 to tear out and disintegrate the coal or other mineral between the top of the vein-attacking and disintegrating mechanism and the mine roof. The elevated position of the vein-attacking and disintegrating mechanism is indicated in dotted lines at D in Fig. 65. During upward 55 swinging movement of the vein-attacking and disintegrating mechanism, the up-swing cylinders 475 apply a rapid and powerful upward thrust to the orbitally moving disintegrating chains so that the coal or other mineral is broken or torn loose in relatively large fragments from the face. Upon completion of the forward swinging operation, liquid may be trapped in the up-swing cylinders 475 and the slide valves 768 may then be positioned to supply liquid under pressure to the forward ends of the feed cylinders 466 to effect withdrawing movement 60 of the vein-attacking and disintegrating mechanism, to 65

retract the latter to the position indicated in dotted lines at E in Fig. 65, to withdraw the outer portion of the vein-attacking and disintegrating mechanism from the coal seam or mine vein. During the sumping, up-swinging and withdrawing operations of the vein-attacking mechanism, the coal or other mineral torn loose by the disintegrating elements of the disintegrating chains is conveyed rearwardly along the top runs of the chains to discharge onto the front loading conveyor 410, by which the disintegrated material is conveyed rearwardly to discharge into the hopper 409. The disintegrated material is conveyed by the rear discharge conveyor 411 from the hopper 409 rearwardly of the apparatus to a suitable point of delivery. During the forward sumping movements of the vein-attacking and disintegrating mechanism, the pusher or shovel 412 moves loose material which has dropped to the mine floor forwardly and causes it to heap up beneath the disintegrating apparatus—then in lowered position and the heap then has its upper portion trimmed off by forwardly moving lower runs of the disintegrating chains, which carry the material around and deposit it on the front conveyor 410. The vein-attacking and disintegrating mechanism, by suitable operation of the swing cylinders 428 under the control of the slide valve 766, may be swung in a horizontal direction about the swivel axis of the swiveled supporting frame or turntable 404, to locate the same in different radial positions so that a series of adjacent vertical segments of coal or other mineral may be suitably removed from the working face until the coal across the entire width of the face has been removed and loaded out. The front conveyor 410 is so arranged with respect to the hopper 409 that it discharges into the hopper regardless of the rectilinear or laterally swung position of the vein-attacking and disintegrating mechanism. During any of the operations above described, the slide valves 763 and 764 may be positioned to control the liquid supply with respect to the cylinders 660 and 680 to effect tilting of the rear discharge end of the rear conveyor and to swing the rear discharge end of the rear conveyor laterally into different positions. During the sumping, up-swinging and withdrawing operations of the vein-attacking and disintegrating mechanism, spray water is delivered through the water pipe 745 from any suitable source of supply to the water chamber 746, and is conducted through the restricted passage means 747 and recesses 748 to the water jets 749, through which the water is sprayed on the coal face in the vicinity of the zone of action of the disintegrating chains. By discharging the spray water outwardly between the disintegrating chains directly within the recess formed in the coal by the disintegrating chains, the dust is effectively allayed. During the vein-attacking and disintegrating operation, the relief valve 777 also serves to protect the mechanism 408 and its supporting structure in the event of roof falls, which might overstress the mechanism and result in possible damage thereto.

As a result of this invention, an improved mining and loading apparatus is provided whereby coal or other minerals may be removed from a solid face of a coal seam or mine vein without the use of explosives, and the dislodged mineral or coal, as it is detached from the mineral vein or coal seam, is continuously conveyed from the vicinity of the working face rearwardly of the apparatus to a suitable point of delivery. By the provision of the novel vein-attacking and disintegrating mechanism and its power operating means, the coal or other mineral may be dislodged or torn from the face in relatively large fragments, greatly expediting the mining operation. The conveyor and receiving means arrangement provides extremely effective means for receiving and collecting the disintegrated coal or other mineral discharged from the vein-attacking and disintegrating mechanism, and the associated conveying means serves to discharge the disintegrated coal or other mineral at desired points rearwardly of the apparatus. The improved pusher means mounted in a novel manner to

move rectilinearly and to swing laterally with the vein-attacking and disintegrating mechanism, effects efficient cleaning up of loose material which has fallen to the mine floor and its delivery by the disintegrating apparatus to the conveyor system. As a result of the arrangement of the motors at the opposite sides of the swiveled support, and the provision of the self-adjusting driving connections between the motors and the vein-attacking and disintegrating mechanism, not only is an extremely low compact construction attained, but also a simple and rugged design is afforded. The apparatus is extremely vertically compact, is readily maneuverable, and is extremely flexible in operation, well adapted to meet the demands of service encountered in mining. These and other advantages of the invention will be clearly apparent to those skilled in the art.

This application is a continuation-in-part of my co-pending application Serial No. 47,421, filed September 2, 1948, now abandoned.

While there are in the application specifically described three embodiments which the invention may assume in practice, it will be understood that these embodiments are shown for purposes of illustration and that the invention may be further modified and embodied in various other forms without departing from its spirit or the scope of the appended claims.

What I claim as new and desire to secure by Letters Patent is:

1. In a mining and loading apparatus, the combination comprising a base movable over the floor of a mine, vein-attacking and disintegrating mechanism for attacking the mineral of a solid mine vein for disintegrating the mineral and for moving the disintegrated mineral away from the mine vein, means for mounting said attacking and disintegrating mechanism on said base to swing in vertical planes relative to said base between the floor and roof levels and for back and forth rectilinear sumping and withdrawal movements longitudinally relative to said base at the floor and roof levels respectively prior to and after such swinging movement of said mechanism, means for moving said attacking and disintegrating mechanism rectilinearly back and forth to effect such sumping and withdrawal movements thereof with respect to the mine vein, means for swinging said attacking and disintegrating mechanism in vertical planes as aforesaid during the attacking and disintegrating operation, loading means on said base for receiving the disintegrated mineral discharged from said vein-attacking and disintegrating mechanism and for discharging the disintegrated mineral from the apparatus, said loading means including conveying means having at least a portion moving rectilinearly back and forth on said mounting means with said attacking and disintegrating mechanism relative to said base and arranged to receive the disintegrated mineral discharged from said attacking and disintegrating mechanism in any of its vertically swung and longitudinal rectilinear positions relative to said base, and a floor clean-up device movable with said mounting means longitudinally rectilinearly back and forth with said attacking and disintegrating mechanism and engaging the loose mineral on the mine floor beneath said mechanism and gathering such mineral for loading onto said conveying means, said floor clean-up device moving forwardly with said attacking and disintegrating mechanism during sumping and retracting with said mechanism during withdrawal thereof as aforesaid, said floor clean-up device comprising a shovel or pusher effective as said mounting means is advanced to pile up the disintegrated mineral on the mine floor beneath said attacking and disintegrating mechanism and to direct a portion of the mineral rearwardly toward said conveying means, said mounting means being swivelly mounted on said base to swing horizontally relative thereto and said attacking and disintegrating mechanism, said portion of said conveying means and said floor clean-up devices all being swingable horizontally in unison with said mounting means to locate

the same in different angular positions relative to said base.

2. In a mining and loading apparatus, the combination comprising a base movable over the floor of a mine, vein-attacking and disintegrating mechanism for attacking the mineral of a solid mine vein for disintegrating the mineral and for moving the disintegrated mineral away from the mine vein, means for mounting said attacking and disintegrating mechanism on said base to swing in vertical planes relative to said base between the floor and roof levels and for back and forth rectilinear sumping and withdrawal movements longitudinally relative to said base at the floor and roof levels respectively prior to and after such swinging movement of said mechanism, means for moving said attacking and disintegrating mechanism rectilinearly back and forth to effect such sumping and withdrawal movements thereof with respect to the mine vein, means for swinging said attacking and disintegrating mechanism in vertical planes as aforesaid during the attacking and disintegrating operation, loading means on said base for receiving the disintegrated mineral discharged from said vein-attacking and disintegrating mechanism and for discharging the disintegrated mineral from the apparatus, said loading means including conveying means having at least a portion moving rectilinearly back and forth on said mounting means with said attacking and disintegrating mechanism relative to said base and arranged to receive the disintegrated mineral discharged from said attacking and disintegrating mechanism in any of its vertically swung and longitudinal rectilinear positions relative to said base, and a floor clean-up device movable with said mounting means longitudinally rectilinearly back and forth with said attacking and disintegrating mechanism and engaging the loose mineral on the mine floor beneath said mechanism and gathering such mineral for loading onto said conveying means, said floor clean-up device moving forwardly with said attacking and disintegrating mechanism during sumping and retracting with said mechanism during withdrawal thereof as aforesaid, said mounting means being swivelly mounted on said base to swing horizontally relative thereto and said attacking and disintegrating mechanism, said portion of said conveying means and said floor clean-up device all being swingable horizontally in unison with said mounting means to locate the same in different angular positions relative to said base, said attacking and disintegrating mechanism including orbitally movable means circulating in parallel vertical orbits and said floor clean-up device being effective to pile up the loose mineral on the mine floor beneath said mechanism as the latter is moved rectilinearly forwardly whereby said mechanism when lowered on its mounting means has its orbitally movable means in contact with the piled-up mineral to effect movement thereof onto said conveying means at a point above and spaced rearwardly of the forward portion of said floor clean-up device.

3. In a mining and loading apparatus, the combination comprising a base movable over the floor of a mine, vein-attacking and disintegrating mechanism for attacking the mineral of a solid mine vein for disintegrating the mineral and for moving the disintegrated mineral away from the mine vein, means for mounting said attacking and disintegrating mechanism on said base to swing in vertical planes relative to said base between the floor and roof levels and for back and forth rectilinear sumping and withdrawal movements longitudinally relative to said base at the floor and roof levels respectively prior to and after such swinging movement of said mechanism, means for moving said attacking and disintegrating mechanism rectilinearly back and forth to effect such sumping and withdrawal movements thereof with respect to the mine vein, means for swinging said attacking and disintegrating mechanism in vertical planes as aforesaid during the attacking and disintegrating operation, loading means on said base for receiving the disintegrated mineral discharged from said vein-attacking and disintegrating mech-

anism and for discharging the disintegrated mineral from the apparatus, said loading means including conveying means having at least a portion moving rectilinearly back and forth on said mounting means with said attacking and disintegrating mechanism relative to said base and arranged to receive the disintegrated mineral discharged from said attacking and disintegrating mechanism in any of its vertically swung and longitudinal rectilinear positions relative to said base, and a floor clean-up device movable with said mounting means longitudinally rectilinearly back and forth with said attacking and disintegrating mechanism and engaging the loose mineral on the mine floor beneath said mechanism and gathering such mineral for loading onto said conveying means, said floor clean-up device moving forwardly with said attacking and disintegrating mechanism during sumping and retracting with said mechanism during withdrawal thereof as aforesaid, said mounting means comprising horizontal guiding means extending forwardly in advance of said base and including parallel horizontal guideways spaced equidistantly from the central longitudinal plane of said attacking and disintegrating mechanism and a support having parallel guides cooperating with said guideways and by which said attacking and disintegrating mechanism is carried, said portion of said conveying means and said floor clean-up device being carried by said support, said conveyor portion extending forwardly and downwardly between said guideways with its forward receiving end mounted on said support beneath said attacking and disintegrating mechanism, said moving means comprising extensible power devices extending longitudinally in parallelism between the outer sides of said conveyor portion and said guideways for moving said support rectilinearly back and forth along said guiding means as aforesaid, motors mounted on said mounting means at the outer sides of said guideways and relative to which said support is rectilinearly movable, and extensible driving connections between said motors and said attacking and disintegrating mechanism for driving the latter in all adjusted positions of said support along said guiding means relative to said motors.

4. In a mining and loading apparatus, the combination comprising a base movable over the floor of a mine, vein-attacking and disintegrating mechanism comprising a series of disintegrating elements movable in closely spaced upright orbital paths for attacking and disintegrating the mineral of a solid mine vein, with said elements moving along the bottoms of said orbits toward the face, along the tops of said orbits away from the face, and upwardly at the forward portions of said orbits, means on said base on which said vein-attacking and disintegrating mechanism is mounted to swing in vertical planes relative to said base between the floor and mine roof, receiving means on said base for receiving disintegrated mineral discharged from said mechanism irrespective of the swung position of said mechanism, a pusher device carried by said mounting means and extending transversely beneath said vein-attacking and disintegrating mechanism and relative to which said attacking and disintegrating mechanism swings for acting upon disintegrated mineral on the mine floor and effective as said mounting means is advanced to thrust such mineral in a direction forwardly of the apparatus into the range of action of said orbitally movable disintegrating elements to cause the latter to move the disintegrated mineral engaged thereby forwardly, upwardly and rearwardly to discharge onto said receiving means, and means for moving said mounting means, said attacking and disintegrating mechanism and said pusher device forwardly in unison during the attacking and floor clean-up operations.

5. In a mining and loading apparatus, the combination comprising a base movable over the floor of a mine, vein-attacking and disintegrating mechanism for dislodging mineral from a solid mine vein, means for mounting said attacking and disintegrating mechanism on said base for

back and forth rectilinear movements with respect thereto toward and from the face of the mine vein, and conveying means on said base for receiving the mineral dislodged and disintegrated by said mechanism comprising a single, continuous, endless conveyor extending from said mechanism rearwardly lengthwise of the apparatus including a front conveyor portion moving back and forth with said attacking and disintegrating mechanism for receiving the disintegrated mineral discharged from said mechanism and a rearward conveyor portion moving in synchronism with said forward portion, and means for moving said rearward conveyor portion upon movement of said forward conveyor portion for coordinating the movements of said rearward conveyor portion with the movements of said forward conveyor portion, said means for coordinating the movements of said conveyor portions including a master cylinder element containing a piston element, said elements having relative reciprocation and one of said elements moving back and forth with said attacking and disintegrating mechanism and said other element being relatively stationary, a slave cylinder element containing a piston element, said slave cylinder and piston elements having relative reciprocation and one of said latter elements being connected to move said rear conveyor portion and said other latter element being relatively stationary, and fluid conduits connecting said opposite ends of said master cylinder element with the opposite ends of said slave cylinder element thereby to provide a closed fluid system so that the master element which moves with said front conveyor portion effects in unison therewith movement of said slave element which moves said rear conveyor portion.

6. In a mining and loading apparatus, the combination comprising a base movable over the floor of a mine, vein-attacking and disintegrating mechanism for dislodging mineral from a solid mine vein, means for mounting said attacking and disintegrating mechanism on said base for back and forth rectilinear movements with respect thereto and for lateral swinging movement relative to said base into different angularly related positions, and conveying means on said base for receiving disintegrated mineral discharged from said attacking and disintegrating mechanism comprising a single, continuous, endless conveyor extending from said attacking and disintegrating mechanism rearwardly toward the rear end of the apparatus, said conveying means including a front conveyor portion movable laterally and rectilinearly back and forth with said attacking and disintegrating mechanism, a stationary rear discharge conveyor portion and an extensible and retractable intermediate conveyor portion laterally flexible into different positions relative to said base, and means responsive to such rectilinear movements of said attacking and disintegrating mechanism for extending and retracting said intermediate conveyor portion with said said front conveyor portion irrespective of the laterally flexed position of said intermediate conveyor portion relative to said base.

7. In a mining and loading apparatus, the combination comprising a base movable over the floor of a mine, vein-attacking and disintegrating mechanism mounted on said base for movements rectilinearly back and forth relative thereto toward and from the face of a mine vein for dislodging mineral from the solid and having supporting means angularly adjustable to change the path of movement of said attacking and disintegrating mechanism relative to said base to enable attack on the face at different points across the latter, means for effecting back and forth rectilinear movements of said attacking and disintegrating mechanism, conveying means on said base for receiving disintegrated mineral from said attacking and disintegrating mechanism, said conveying means including an endless conveyor and guiding means therefor, said conveyor having a forward conveyor portion closely adjacent to and moving rectilinearly back and forth with said attacking and disintegrating mechanism and laterally adjustable

with the latter into different face-attacking positions as aforesaid, a movable rear discharge conveyor portion and an intermediate conveyor portion, and means respectively controlled by the angular adjustments of said attacking and disintegrating mechanism for attacking the face at different laterally disposed points as aforesaid and by said means for moving said attacking and disintegrating mechanism rectilinearly back and forth relative to the face and automatically responsive to such movements for controlling said rear discharge portion to maintain requisite tension in said endless conveyor.

8. In a mining and loading apparatus, the combination comprising a base movable over the floor of a mine, a supporting structure mounted on said base to swing horizontally with respect thereto about an upright axis, a frame guided on said supporting structure for movement rectilinearly back and forth relative thereto along a line extending radially with respect to said upright axis, vein-attacking and disintegrating mechanism carried by said frame for rectilinear movement therewith toward and from the face of the mine vein for dislodging mineral from the solid, conveying means on said base for receiving disintegrated mineral discharged from said attacking and disintegrating mechanism and including a forward conveyor portion moving rectilinearly back and forth with said frame, a rearward discharge conveyor portion having a relatively fixed discharge end and an extensible and retractable intermediate conveyor portion, means for moving said frame rectilinearly back and forth relative to said supporting structure to effect feed and retraction of said attacking and disintegrating mechanism with respect to the mine vein, and means including a power device actuated by said moving means and engaging said intermediate conveyor portion for extending and retracting said intermediate conveyor portion, said power device of said extending and retracting means including fluid actuated cylinder and piston elements, oppositely acting fluid cylinder and piston elements and conduit means for connecting said elements whereby relative movement of the first mentioned elements effects relative actuation of said second mentioned elements.

9. In a mining and loading apparatus, the combination comprising a base movable over the floor of a mine, a supporting structure mounted on said base to swing horizontally with respect thereto about an upright axis, a frame guided on said supporting structure for movement rectilinearly back and forth relative thereto along a line extending radially with respect to said upright axis, vein-attacking and disintegrating mechanism carried by said frame for rectilinear movement therewith toward and from the face of the mine vein for dislodging mineral from the solid, conveying means on said base for receiving disintegrated mineral discharged from said attacking and disintegrating mechanism and including a forward conveyor portion moving rectilinearly back and forth with said frame, a rearward discharge conveyor portion having a relatively fixed discharge end and an extensible and retractable intermediate conveyor portion, means for moving said frame rectilinearly back and forth relative to said supporting structure to effect feed and retraction of said attacking and disintegrating mechanism with respect to the mine vein, and means including a power device actuated by said moving means and engaging said intermediate conveyor portion for extending and retracting said intermediate conveyor portion, said power device of said extending and retracting means including a master fluid cylinder and piston mechanism actuated by said moving means and a slave fluid cylinder and piston mechanism having its cylinder means connected in communication with said master cylinder whereby the slave mechanism is actuated by the master mechanism, and connections between said slave mechanism and said intermediate conveyor portion.

10. In a continuous mining apparatus, the combination comprising a base movable over the floor of a mine, a

frame structure mounted on said base to swing horizontally with respect thereto about a vertical axis and providing guiding means extending radially with respect to the swivel axis of said frame structure and projecting in advance of said base, a support mounted on said swiveled frame structure to swing horizontally therewith relative to said base and to move rectilinearly back and forth along said guiding means, a vein-attacking and disintegrating mechanism pivotally mounted on said support to swing in vertical planes with respect thereto for attacking and disintegrating the mineral of a solid mine vein and including disintegrating means having disintegrating elements movable in parallel vertical orbits, conveying means mounted on said base for receiving the disintegrated mineral dislodged from the mine vein by said attacking and disintegrating mechanism, and driving means for said disintegrating means for effecting such orbital movement of the disintegrating elements thereof comprising a pair of motors, one arranged at each side of said swiveled frame and operatively connected to said disintegrating means whereby both motors effect drive thereof, said conveying means having a forward conveying portion disposed on said support intermediate said motors and extending downwardly beneath the said attacking and disintegrating mechanism with its forward receiving portion extending downwardly toward the mine floor below said attacking disintegrating mechanism, said forward conveying portion moving back and forth with said support and said attacking and disintegrating mechanism relative to said swiveled frame and said forward conveying portion receiving the disintegrated mineral and moving the same upwardly and rearwardly in the space between said motors toward the swivel axis of said frame, and said conveying means having a rearward conveying portion for conveying the mineral rearwardly of said swivel axis to discharge at a rearward point of delivery.

11. In a continuous mining apparatus, the combination comprising a base movable over the floor of a mine, a frame structure mounted on said base to swing horizontally with respect thereto about a vertical axis and providing guiding means extending radially with respect to the swivel axis of said frame structure and projecting in advance of said base, a support mounted on said swiveled frame structure to swing horizontally therewith relative to said base and to move rectilinearly back and forth along said guiding means, a vein-attacking and disintegrating mechanism pivotally mounted on said support to swing in vertical planes with respect thereto for attacking and disintegrating the mineral of a solid mine vein and including disintegrating means having disintegrating elements movable in parallel vertical orbits, conveying means mounted on said base for receiving the disintegrated mineral dislodged from the mine vein by said attacking and disintegrating mechanism, and driving means for said disintegrating means for effecting such orbital movement of the disintegrating elements thereof comprising a pair of motors, one arranged at each side of said swiveled frame and operatively connected to said disintegrating means whereby both motors effect drive thereof, said conveying means having a forward conveying portion disposed on said support intermediate said motors and extending downwardly beneath the said attacking and disintegrating mechanism with its forward receiving portion extending downwardly toward the mine floor below said attacking and disintegrating mechanism, said forward conveying portion moving back and forth with said support and said attacking and disintegrating mechanism relative to said swiveled frame and said forward conveying portion receiving the disintegrated mineral and moving the same upwardly and rearwardly in the space between said motors toward the swivel axis of said frame, said swiveled frame having upstanding side portions disposed in parallelism with said guiding means with the latter disposed between said side portions, said

upstanding side portions disposed at the outer sides of said forward conveying portion and the space for the passage of disintegrated mineral being conveyed by said forward conveying portion being disposed intermediate 5 said upstanding side portions, said motors being mounted on said upstanding frame portions at their outer sides with the bottoms of said motors overlying and spaced vertically from said base and the tops of said motors disposed no higher than the top of said support.

12. In combination, supporting means movable over the floor of a mine, a frame mounted on said supporting means to move horizontally in a longitudinal direction relative thereto, a mineral disintegrating head pivotally mounted on said frame to swing in vertical planes with respect thereto, said head comprising a head frame and a series of parallel disintegrating chains guided for orbital circulation relative to said head frame, the lower runs of said chains moving forwardly longitudinally along the bottom of said head frame and the top runs of said chains 15 moving rearwardly longitudinally along the top of said head frame, conveying means on said movable frame for receiving the disintegrated mineral discharged rearwardly from the top runs of said chains, a floor cleanup device carried by said movable frame and extending forwardly 20 and downwardly beneath said head into adjacency to the mine floor for cleaning up any loose mineral which has fallen to the mine floor from said head, means for advancing said frame horizontally to cause said floor clean-up device to engage the loose mineral on the mine floor to pile up such mineral in the paths of the lower 25 runs of said chains and for directing a portion of the gathered mineral toward the forward portion of said conveying means, said conveying means receiving the mineral discharged from said head at a point spaced a substantial distance rearwardly from its forward portion, 30 the lower runs of said chains engaging the piled-up mineral to move the same forwardly and upwardly to the top of said head frame wherein it is moved rearwardly by the top runs of said chains.

13. A combination as set forth in claim 12 wherein said supporting means includes a horizontally swingable support swiveled on an upright axis and said movable frame is guided for movement rectilinearly relative to said swingable support in a direction extending radially 45 of said upright axis.

14. In combination, supporting means, a forward frame swivelly mounted on said supporting means to swing horizontally relative thereto, a second frame mounted on said frame to move horizontally back and forth to retract 50 and extend relative thereto, a rearward frame movably mounted on said supporting means, an endless conveyor guided for orbital circulation relative to said three frames, said frames providing guideways for said endless conveyor, means automatically effective as said forward frame 55 portion is swung horizontally relative to said other frames for maintaining the tension of said conveyor and including a shiftable element responsive to swinging movement of said forward frame, and means automatically effective when said second frame moves horizontally back 60 and forth relative to said swivelled frame for coordinating the movement of the rearward frame with the movement of said forward frame, said movement coordinating means including a power operated element responsive to back and forth movement of said second frame and 65 operatively connected with said shiftable element of said tension maintaining means.

15. A combination as set forth in claim 14 wherein said power operated element is in the form of a movable part of an extensible power jack.

16. A combination as set forth in claim 15 wherein said extensible power jack comprises relatively reciprocable fluid cylinder and piston elements, and said movement coordinating means comprises cooperating fluid cylinder and piston elements cooperating to provide a device for supplying fluid under pressure to said cylinder element

of said tension maintaining means upon horizontal longitudinal movement of said frame, and fluid conducting means is connected between said cylinder elements whereby fluid may flow from one cylinder element to the other.

17. A combination as set forth in claim 16 wherein said shiftable element comprises a cam actuated strut guided for movement longitudinally of said swingable conveyor portion and shifted endwise upon swinging of said conveyor portion, and said cylinder element of said movement coordinating means is carried and actuated by said strut.
